CLARENCE E. LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed March 16, 1921, Serial No. 452,840. Renewed July 20, 1925.

The present invention relates in general to automatic telephone systems, but more particularly to small automatic systems of the type commonly used for giving telephone service in factories, business houses, or other private establishments; and the object of the invention, broadly stated, is to provide a private automatic exchange system embodying new features and novel circuit arrangements for giving effect to these features, whereby a system is produced which is better adapted than others to fill the commercial requirements of the present time.

The principal object in mind, during the design of the circuits, was to produce a private automatic exchange system which will operate without change in conjunction with either a manual or automatic main exchange. The importance of this will be appreciated from the fact that at present a great many manual systems are being replaced by automatic systems, and from the probability that eventually all manual systems will be so replaced. Under these conditions, operating telephone companies desire to have such new private branch exchange installations as they make from time to time of such a character that they will continue to give service without change during and after the substitution of the automatic equipment in the main exchange.

According to the present invention an operator is employed to complete main to branch exchange connections and a further feature is an improved arrangement for giving "night service" when the operator is away from her position. A minor feature in this connection is an arrangement whereby certain local lines are denied access to the main exchange trunk lines at ordinary times during the day, while all the local lines are given access to such trunk lines when the night service connections are up.

A further feature is concerned with a well known type of conference calling arrangement, and involves a saving in apparatus over the schemes formerly known to applicant.

Still other features relate to novel means for making a trunk line busy to local switches when it is taken for use at the main exchange; to an improved means for controlling the disconnect signals in the branch exchange cord circuits; to an improved ar-

angement for giving the main exchange operator supervision on main to branch exchange calls; to a novel method of controlling a locking ring down relay over a trunk line so that the same can be unlocked from the distant end; and to new circuit arrangements for supplying talking current to branch exchange subscribers when they are called from the main exchange.

There are still other features not now specifically mentioned but which, together with the above, will be described fully hereinafter with reference to the accompanying drawings.

In order to fully illustrate and describe the invention it has been shown in conjunction with a manual main exchange which it is assumed is about to be cut over to automatic operation. As stated hereinbefore, the circuits of the invention have been designed to work in conjunction with either a manual or an automatic main exchange and it is understood, therefore, that at the time of the cut over no change is necessary in the apparatus at the private automatic exchange. Prior to the cut over all telephone lines in the manual main exchange are equipped for automatic service by the installation of individual line switches and the usual automatic equipment. Before the cut over and while the automatic equipment is being installed the cut off relays in the subscribers' individual line switches are mechanically placed in an operated position so that up to the time of the cut over the exchange will work manually in the usual manner. When the time for the cut over arrives new directories are issued, the subscribers are notified through the medium of local newspapers or any other convenient means, and are advised that in making calls after the set time they will have to operate the calling devices at their telephones. In the exchange the cut off relays on the line switches are restored to their normal condition and the lines leading to the manual equipment are cut, or otherwise disconnected. Thereafter the exchange operates in the usual automatic manner.

Figures 1 to 4 show a system embodying the invention and should be arranged in order with Figure 1 at the left.

Referring now to the drawings, in Fig. 1 is shown a subscriber's telephone A² having

the manual line equipment terminating in jack J^{10} and the automatic individual line equipment or line switch C^2 . The jack J^{10} appears at some A operator's position, and there are also the usual multiple jacks, either at the A board or at a so called B board, depending on the size of the system. These arrangements are well known and on that account only the answering jack is shown.

10 The cord circuit O is of a well known type and is used for extending the line of any subscriber to that of another subscriber or to trunk lines leading to other exchanges. The jack J^{11} is a terminal of such a trunk line extending to a private automatic exchange. The line switch C^2 is of the well known rotary type and has access to trunk lines terminating in selector switches similar to the one shown at E. The selector E 15 is of the usual Strowger vertical and rotary type and has access to trunk lines terminating in connector switches one of which is shown at H^2 , Fig. 2.

20 The connector H^2 is of the well known Strowger type and has access to main exchange subscribers' lines, one of these being shown at A^3 , and to trunk lines leading to the private automatic exchange. The bank contacts 25 585-588, inclusive, represent terminals of such a trunk line which is the same as the one terminating in jack J^{11} before the operator. This trunk line extends to the private automatic exchange where it terminates in jacks J' and J^2 , Fig. 3, at the attendant operator's position.

25 At O' , Fig. 3, is shown the cord circuit at the attendant operator's position in the private automatic exchange. The auxiliary jack J' of the trunk is used for night service only. The jack J^2 is the terminal of a trunk line extending to an incoming automatic connector switch which is shown at H , Fig. 40. This connector is of the usual Strowger type having access to local subscribers' lines 45 such as that of the substation A' . At A, Fig. 4, is shown an automatic substation of the usual type having the rotary line switch C individual thereto. The line switch C in common with a plurality of other line 50 switches has access to trunk lines terminating in the local connector selector repeaters, one of these being shown at H' , Fig. 4. This switch is of the well known Strowger type having 100 bank contacts arranged in ten 55 rows or levels. On the first eight levels this connector has access to local subscribers' lines as has the connector H. These local lines are, of course, multiplied in the usual manner throughout all the connector switches. 60 On the ninth level the connector H' has access to ring down trunks going to another manual exchange. On the tenth level are accessible trunk lines leading to the main exchange. As shown, the bank contacts 65 370-372, inclusive, represent the terminal of

such a trunk line, being the same one as is shown connecting Figs. 2 and 3.

Although the wiring of the banks of the switch H' will be readily understood, it will be briefly explained. The bank contacts 370-372, inclusive, are the terminals of the trunk line leading to the public manual exchange, Figs. 1 and 2, and as shown are the multiples of the trunk line shown incoming to Fig. 3. The bank contacts 375-377, inclusive, are the terminals of a trunk line leading to another manual exchange. The conductors leading from the bank contacts 379-381, inclusive, terminate in the night service equipment shown at N, Fig. 3. Bank contacts 384-386, inclusive, are the terminals of the conference number in the connector H' .

Having briefly described the apparatus in which the invention is involved a detailed description of its operation will now be given. The description will first be given according to the assumption that the main exchange is operating manually, and it will be assumed that the subscriber at substation A^2 in the main exchange desires to call the subscriber at substation A' (Fig. 4) in the branch exchange.

Calls from the manual main exchange to the 95 private automatic exchange.

When the receiver is removed at substation A^2 a circuit is completed for line relay 409 over the line conductors 401 and 402 in series. Upon energizing, relay 409 at armature 412 lights the line lamp L^{10} before an operator. This operation signals the operator at whose position the answering jack J^{10} appears and she will respond to the call by inserting the answering plug of an idle cord circuit, the cord circuit O for example, into the answering jack J^{10} . When the plug is inserted into the jack the cut off-relay 410 is energized, the circuit of the line relay 409 is broken and the line lamp L^{10} is extinguished. At the same time a circuit is completed over the sleeve of the cord for the answering supervisory lamp L^{11} but since the receiver is off the hook at substation A^2 the supervisory relay 420 will at once operate and shunt 110 the lamp L^{11} to prevent it from lighting at the present time. The operator may now throw the listening key K^5 in the cord circuit O in order to answer the calling subscriber and ascertain what number he desires. Having 115 found that the desired party is the subscriber at substation A' in the distant private automatic exchange the operator will test the jacks associated with the trunk lines extending to such exchange with the tip of the calling plug in the usual manner and she will insert the plug in the first idle jack. Assuming that the trunk line shown in the drawing is the first idle trunk line the calling plug P^{11} will be inserted into the jack 120 125 130

J¹¹. A circuit is thereby completed for the cut off relay 426 over the sleeve of the cord. The answering supervisory lamp L¹² is included in this circuit and hence operates.

5 Relay 426, upon energizing, disconnects the normal battery and ground connections from the trunk conductors 428 and 429 at armatures 611 and 610 and at armature 430 completes the circuit of the slow acting relay 427. The latter relay, upon energizing, opens a point in the circuit of the line lamp L¹³ associated with the trunk line at armature 433 and at the front contact of this armature prepares a locking circuit for itself 10 and at armature 432 removes one connection of ground to the cut off relay. However this latter operation is without function at this time as ground is still connected to the cut off relay from the back contact of armature 435 of the line relay 425. The battery supplied by the operator's cord circuit to the trunk conductors 428 and 429 is of opposite polarity to that normally supplied when the trunk line is not in use. The relay 27 in the 15 trunk circuit at the private automatic exchange is a high resistance polarized relay, normally energized by the battery on the trunk and consequently it will retract its armature 38 and close its associated contacts 20 whenever battery is removed from the trunk or reversed thereover. It will be seen that by this arrangement should the trunk accidentally go open or be seized by an operator, as in the present case, the relay 27 will 25 30 35 retract its armature. In either case, upon deenergizing, relay 27 completes a circuit extending from ground by way of back contact and armature 34, armature 38 and its resting contacts and thence through the winding of the slow acting relay 28 to battery. Upon energizing, this latter relay at armature 40 places ground on release trunk conductor 136 extending to local connector switches such as the connector H' thereby 40 45 50 55 60 65 70 75 80 85 90 95 100 105 110 115 120 125 130 making the trunk line busy for any outgoing calls and at armature 39 completes a point in the talking connection. The main exchange operator will now operate her ringing key K⁶ thereby impressing ringing current upon the trunk. This will serve to operate the ring up relay 25 which energizes, establishes a locking circuit for itself at armature 32, and at armature 31 completes the circuit of the line lamp L'. It will be seen that the relay 25 at armature 33 also short circuits the condenser thereby placing its lower winding in bridge of the trunk conductors. However its lower winding is of such high resistance that the supervisory control relay 421 in the calling operator's cord circuit is not energized. If for any reason the main exchange operator withdraws the plug P¹¹ from the jack J¹¹ before the attendant has answered the cut off relay 426 will deenergize restoring the

normal battery supply to the trunk conductors. This operation will consequently reverse the direction of current flow in the lower winding of relay 25. As the magnetic fields produced by the windings of relay 25 now oppose each other this relay will deenergize. It will be understood, of course, that the armatures 32 and 33 are so adjusted that they break away from their front contacts simultaneously, thus any fluttering of the relay armatures is prevented. By the deenergization of relay 25, the line lamp L' is effaced and thus all apparatus is returned to normal.

It will now be assumed that the branch exchange operator notices the lighting of the line lamp L'. This signal will serve to notify the attendant operator in the private automatic exchange that a connection is desired and she will, therefore, insert the plug of an idle cord circuit, which we will assume is the plug P of the cord circuit O', into the jack J². By this operation a circuit is completed extending from ground through the winding of relay 50 by way of the sleeve of the plug P, sleeve of the jack J², and thence through the winding of relay 26 to battery in multiple with the busy visual 29. Upon energizing, relay 26 opens the locking circuits of the ring up relay 25 at armatures 35 and 36 and at armature 34 opens a point in the circuit of relay 28 but the springs 71 are closed by the plug P being shoved into the jack J² so this operation has no effect at this time. The locking circuits of the relay 25 now being open this relay will deenergize thereby extinguishing the lamp L'. The operation of the busy visual is without function at this time. Relay 50 upon operating, completes a circuit extending from ground by way of front contact and armature 60, spring 77 of key K and its resting contact, armature 71 and its back contact, and thence through the answering supervisory lamp L⁶ to battery. When the plug P is inserted in the jack J² a bridge is placed across the talking conductors, the circuit of which may be traced from the tip of plug P, spring 76 and its resting contact, winding of relay 53, winding of relay 52, back contact and armature 70, winding of relay 54, resting contact of spring 75 and the said spring, and thence to the ring of plug P. As battery is now supplied to the trunk from the windings of the repeating coil in the main exchange operator's cord circuit, relay 52 energizes. Owing to the high resistance of relay 52, relays 53 and 54 in the attendant's cord circuit and the supervisory control relay 421 in the calling operator's cord circuit are not operatively energized at this time. Relay 52 upon operating, opens a point in the circuit of relay 51. It will be seen that the circuit of relay 51 is broken by the energization of relay 52 before relay

51 has had time to energize and so this relay is not operated at this time. The attendant operator will now throw the listening key K' thereby associating her head set with 5 the cord circuit and enabling her to ascertain what number the main exchange operator desires. When the key K' is thrown the high resistance relay 52 is shunted out and the relays 53, 54, in the attendant's cord 10 circuit O' are energized while the supervisory control relay 421 in the cord circuit O at the main exchange is also operated. The operation of relay 421 serves to extinguish the supervisory lamp L¹² in the cord-circuit 15 O thereby notifying the main exchange operator that the attendant has answered. Relay 53, upon operating, at armature 67, closes another short circuit around the relay 52 so that even when the key K' is restored 20 to normal the supervisory lamp in the main exchange operator's cord circuit will remain extinguished until the called subscriber has answered and finally hung up. Relay 54, upon energizing, serves to maintain a point 25 in the circuit of relay 51 open, thus preventing this relay from energizing. When the attendant operator finds out what number is desired she will insert the plug P' 30 into an idle jack, which we will assume is jack J³ extending to the incoming connector switch H, Fig. 4. By this operation a circuit is completed for the line relay 150 of the connector H over a circuit which extends from ground by way of normally closed 35 springs controlled by relay 80', springs of the calling device S, key K², spring 79 and its working contact, sleeve of the plug P', sleeve of the jack J³, springs 80, conductor 126 and thence through the winding of the 40 line relay 150 to battery. The line relay 150 will energize over this circuit completing the circuit of the slow acting relay 151, which energizes to prepare the circuit of the switch H for operating. It will be noted 45 that the line relay 150 is not connected directly to the sleeve of the jack J³, this provision is made so that there will be no impulse sent to the line relay 150 due to a contact being made between the tip of the plug 50 P' and the sleeve of jack J³ while the plug is being inserted into the jack J³. Ground is of course present on the tip of the plug P', being supplied from the cord circuit in the main exchange. Thus no impulses will be 55 sent to the line relay 150 until the operator operates her calling device.

The attendant operator may now operate her calling device S in accordance with the first digit of the desired subscriber's number thereby producing a corresponding series 60 of interruptions in the above traced circuit of the line relay 150 which deenergizes a plurality of times in response thereto. At each retraction of its armature 170 a circuit 65 is completed extending from ground by way

of armature 170 and its back contact, armature 173 and its front contact, off normal springs 178 and 179, through the winding of the vertical magnet 161 and then through the winding of the slow acting series relay 70 152 to battery. The above is the circuit over which the first vertical impulse is transmitted. Upon the first vertical step of the shaft, the off normal springs are 75 shifted and the remaining impulses to the vertical magnet traverse a different circuit which is the same as the one previously traced except that it includes the off normal springs 178 and 180, and armature 187 and its front contact, relay 152 being now in an 80 operated position. Magnet 161 operates to raise the wipers 215-218, inclusive, step by step until they are placed opposite the level of bank contacts in which is located the terminals of the line of the substation A'. 85 The slow acting relay 152, which is energized in series with the vertical magnet, maintains its armature attracted throughout the vertical movement of the switch and at the termination thereof deenergizes and 90 transfers the operating circuit to the rotary magnet 162.

The attendant operator may now operate her calling device in accordance with the final digit of the called subscriber's number, as before, producing a series of interruptions in the circuit of the line relay 150 which deenergizes a plurality of times in response thereto. Upon each deenergization, a circuit is completed extending from ground by way of armature 170 and its back contact, armature 173 and its front contact, off normal springs 178 and 180, armature 187 and its back contact, back contact and armature 196, through the winding of the slow 95 acting relay 155, armature 209 and its back contact, and through the winding of the rotary magnet 162 to battery. Magnet 162 operates to rotate the wipers 215-218, inclusive, into engagement with the set of bank contacts associated with the line of the subscriber at substation A' which, we will assume, are the bank contacts 220-223, inclusive. The slow acting relay 155 is energized in series with the rotary magnet and 100 operates to connect the test wiper 217 to the test relay 154. If the desired subscriber's line should be busy at this time a ground potential will be present on the bank contact 222. A circuit may then be traced extending from the said grounded test contact by way of the test wiper 217, armature 201 and its front contact, and through the winding of the test relay 154 to battery. Relay 154 energizes over this circuit establishing a locking circuit for itself at armature 195 and at armature 198 placing the 105 busy tone on the lower line conductor 127. This tone will flow back to the attendant operator and to the calling subscriber and 110 115 120 125 130

serve to inform them that the desired line is busy. Should the calling subscriber at substation A² now desire a connection with another subscriber in the branch exchange 5 he will inform the attendant of this fact. The attendant will then operate the release key K² thereby opening the circuit of the line relay 150 of the connector H. When this relay deenergizes the slow acting release relay 151 deenergizes shortly after, and the connector switch is released in the well known manner. The operator may now by operating her calling device for the digits of desired subscriber's number cause 10 the connector H to connect with this line. The operation in this case is identically the same as that just described and will be readily apparent.

However should the calling subscriber at 20 substation A² replace his receiver the supervisory signal in the cord circuit O would be operated and the operator would withdraw the plugs P¹⁰ and P¹¹ of the cord circuit O from the jacks, thereby causing 25 the lamp L⁵ in the attendant's cord to become lighted. The attendant operator, upon receiving the disconnect signal, withdraws the plugs P and P', thereby releasing all the apparatus. These operations will 30 be described fully hereinafter.

It will now be assumed that the line of the subscriber at substation A' was idle when connection thereto was attempted. Under these circumstances, there will be no 35 ground potential on the test contact 222 and no circuit will be completed for the test relay 154. Then, following the deenergization of the slow acting relay 155, a circuit is completed extending from ground on release 40 trunk conductor 185, by way of normally closed springs controlled by relay 152, armature 195 and its back contact, through the lower winding of the switching relay 156, back contact and armature 201, test wiper 45 217, test contact 222, through the winding of the switching relay 225 of the line switch C', and thence through the winding of the stepping magnet 227 to battery. The relays 156 and 225 operate over this circuit. 50 However, due to a mechanical interlocking device controlled by the armature of the line relay 226 which has not been energized, the switching relay 225 only attracts its armatures enough to disconnect the line of 55 substation A' from its normal battery and ground connections in the line switch C'. Relay 156, upon energizing, establishes a locking circuit for itself at armature 207, places ground on the test wiper 217 at armature 208, and at armatures 205 and 210 completes the ringing circuit.

Having completed the desired connection the attendant operator may now restore her listening key K'. This operation opens the 60 first shunt around the high resistance relay

52 but as the relay 53 is energized the relay 52 is maintained short circuited by the armature 67. In this manner the supervisory signal in the cord circuit O of the main exchange operator is not again operated. 70

Returning now to the operation of the connector H, ringing current is then intermittently applied to the line of the substation A' until an answer is obtained. When this occurs a circuit for direct current is 75 completed over the called subscriber's line for the ring cut off relay 153. Upon energizing, this latter relay establishes a locking circuit for itself at armature 191 and at armatures 190 and 192 cuts off the ring 80 and at the front contacts of these armatures finally completes the talking connection.

When the ring cut off relay 153 in the connector H energizes, a direct metallic circuit extends from the repeating coil in the 85 cord circuit O to substation A'. This circuit it will be seen, includes the relays 54 and 55 in the cord circuit O'. Relay 55, upon operating, opens the bridge extending 90 through relays 52, 53, and 54 at armature 70. Relay 53 restores, but since relay 54 is in series with the lower talking strand, it remains operated to maintain the circuit of relay 51 open after relay 53 restores. Relay 53, in restoring, removes the shunt from 95 relay 52 to permit this relay to operate later on. Relay 55 also at armature 71' opens the circuit of the supervisory lamp L. This latter operation serves to notify the attendant that the called subscriber has answered. 100 The conversation may be carried on over the heavy talking conductors between the main exchange subscriber at substation A² and the subscriber at substation A', battery being supplied to the subscriber at substation A' through the right hand windings 105 of the repeating coil in the cord circuit O of the main exchange operator and to the main exchange subscriber from the left hand windings of the same repeating coil. 110

When the conversation is terminated, both subscribers will replace their receivers upon their switchhooks. Upon the receiver being replaced at the calling substation A², the supervisory control relay 420 is deenergized and the lamp L¹¹ is lighted. When the receiver is replaced at the called substation A' the supervisory relays 54 and 55 in the cord circuit O' deenergize. Relay 55, upon retracting its armatures, closes the circuit of the supervisory lamp L⁶ and places the relays 52, 53 and 54 again across a bridge of the cord circuit. Owing to the high resistance of this bridge, the relay 52 not having 115 its winding shunted at this time, relays 54 and the supervisory control relay 421 in the cord circuit O are deenergized. By the deenergization of relay 421 the lamp L¹² is 120 lighted. The relay 52 again operates and at its armature 64 opens a point in the cir- 125 130

cuit of relay 51 before slow release relay 54 has deenergized. The operator in the main exchange, upon noting the lighting of the lamps L^{11} and L^{12} , will withdraw the 5 answering and calling plugs of the cord circuit O from the jacks J^{10} and J^{11} thereby 10 restoring the apparatus in the main exchange to normal. Immediately upon the plug P^{11} being withdrawn from the jack J^{11} , the cut off relay 426 deenergizes, the 15 circuit of the slow acting relay 427 is opened, and the normal battery connections are replaced on the trunk conductors 428 and 429. When this reversal takes place the 20 relay 52 in the cord circuit O' momentarily deenergizes and completes a circuit extending from ground by way of front contact and armature 60, springs 77, back contact and armature 66, armature 64 and its back 25 contact, armature 72 and its back contact, normally closed springs controlled by armature 61, and thence through upper winding of the relay 51 to battery. The relay 51, energizes over this circuit and, upon operating, establishes a locking circuit for itself at armature 61, at armature 62 closes a low 30 resistance bridge across the trunk conductors, and at armature 63 lights the calling disconnect signal L^5 . The low resistance 35 bridge placed across the trunk conductors by the energization of the relay 51 serves to energize the line relay 425 of the trunk circuit in the main exchange. A locking circuit is then completed for the slow acting 40 relay 427 at armature 435. It will be understood that the relay 427 being slow acting does not retract its armatures before the line relay 425 has had time to energize. Relays 425 and 427 now being energized the 45 circuit of the cut off relay 426 is opened at armatures 432 and 435 and a busy potential is placed on the sleeve of the jack J^{11} associated with this trunk line, at armatures 434 and 431. Now should the main exchange operator try to connect with this 50 trunk line she will receive a busy test. In this manner the trunk line is prevented from being seized until the branch exchange operator has finally taken down the connection in the branch exchange.

Upon noting the signals L^5 and L^6 , the attendant operator will know that the conversation is terminated and she will withdraw the plugs of the cord circuit O' from 55 their associated jacks.

By this last operation the connector H and all the apparatus in the branch exchange is released. As soon as the plug P is withdrawn from the jack J^2 the relays 26 60 and 28 are deenergized, the busy potential is thus removed from the multiplied release trunk conductor in the outgoing level of the local connector switches and the polarized and ring up relay 25 and 27, respectively, 65 are replaced across the trunk conductors.

In the main exchange the line relay 425 deenergizes due to the low resistance bridge through relay 51 having been broken, thus opening the locking circuit of the slow acting relay 427, removing the busy test from the jack J^{11} , and replacing the ground connection of the cut off relay. In the above manner all apparatus is returned to normal. 70

The connector H is also arranged so that it may be used for rotary service, that is, 75 it can select and connect with an idle line in a group of lines or should all lines in a group be busy, notify the calling subscriber of this fact. Its operation in this case is well known and similar to that of the connector H^2 , Fig. 2, the operation of which 80 will be described fully hereinafter.

It will be noted that the connector H' which has access to the same lines as the connector H is not arranged for rotary service. The reason for this is that incoming 85 calls are often important and if certain numbers are called it is often the practice to enable the connector H to connect with any idle one of a number of telephones. Inside 90 calls are not usually so important and any subscriber in the branch exchange will know these other numbers anyway and he can call them separately.

Night service calls from the manual main exchange to the private automatic exchange.

The above is the normal operation of the 95 system when the attendant operator is on duty. During the night, however, there will probably be no operator in charge and so provision must be made for night calls. This is secured by means of the night cord O^2 . The operator, upon going off duty, will 100 place the plugs P^2 and P^3 of the night cord O^2 into the jacks J' and J^4 , respectively. By this operation the night circuits are 105 completed. The operation of the system under these conditions will now be described. 110

For this purpose it will again be assumed that the subscriber at substation A^3 desires to call the private automatic exchange. When the receiver is removed at the calling 115 substation the line relay 409 is energized and the line lamp lighted. As before, the operator at whose position the lamp appears will insert the answering plug of an idle cord circuit O into the jack J' and 120 operate her listening key. Upon being informed that the branch exchange is desired the operator will test the jacks of the trunk lines extending to the private automatic exchange and insert the calling plug of the 125 cord circuit O into the jack of the first idle trunk line, causing the operation of the polarized relay 27 in a manner hereinbefore described. Upon operating, this relay completes the circuit of the slow acting relay 28 which energizes to apply a busy potential 130

to the release trunk of the outgoing trunk line which is accessible to the local switches. It will be seen that by the insertion of the plug P^2 into the jack J' the springs 15 are opened and the ring up relay 25 is therefore removed from across the trunk conductors. When the operator presses her ringing key K^6 ringing current will flow over the trunk conductors 428 and 429, jack J' , cord circuit O^2 , jack J^4 , and thence through the bells 98, 99 and 100. A plurality of these bells are located at convenient places throughout the factory and serve to notify the watchman or whoever is in charge at night that a call is being made. A special number is provided for this service arrangement and the watchman will of course be aware of this number. Upon hearing the night bells ring he will go to the nearest telephone, which we will assume is the substation A, remove his receiver, and operate his calling device for the number assigned to night service.

When the receiver is removed at substation A a circuit is completed for the line relay 260 of the individual line switch C over the line conductors 250 and 251 in series. Upon energizing, the line relay at armature 266 completes a circuit which includes the switching relay 261 and the stepping magnet 262 in series and at armature 265 connects the test wiper 277 to the above circuit at a point midway between the switching relay and the said stepping magnet. The operation of the rotary line switch C now depends upon whether or not the trunk line with which the wipers 275-278, inclusive, are associated is or is not busy. If busy, a ground potential will be present on the test contact engaged by test wiper 277, the switching relay 261 will be short circuited, and the stepping magnet being supplied with direct ground by way of the said test wiper will operate as a buzzer to advance the switch step by step in search of an idle trunk line. It will be assumed in the present case that the trunk line leading from bank contacts 280-283, inclusive, is idle and it will be further assumed that this trunk is selected for use by the line switch C. When this occurs the switching relay 261, being no longer short circuited, will energize in series with the said stepping magnet. It may be stated at this time that the switching relay is of very high resistance so as to prevent the operation of the stepping magnet. Upon energizing, the switching relay 261 disconnects the line conductors 250 and 251 from the winding of the line relay and from ground, respectively, and extends them by way of armatures 268 and 271 and their front contacts, wipers 275 and 278, bank contacts 280 and 283, and through the upper and lower windings of the line relay 300 of the local connector selector repeater H' . The line relay 300 will energize over the line circuit and at armature 315 complete the circuit of the slow acting relay 301 which energizes preparing the operating circuits of the switch H' at armature 319, and at armature 318 places ground on the release 70 trunk conductor 320 thereby establishing a holding circuit which extends by way of bank contact 282, test wiper 277, armature 270 and its front contact, through the winding of the switching relay 261 and the 75 winding of the stepping magnet 262 to battery. A branch of this circuit also extends by way of the private normal conductor 252 to multiply connected test contacts in the banks of local connector switches such as the 80 switch H' and similar switches which have access to the line of the substation A. This multiple has not been shown for the reason that it is well known and would unduly complicate the drawings. It will be understood of course, that the above holding circuit is completed before the deenergization 85 of the line relay 260.

The watchman will now operate the calling device at substation A in accordance with 90 the first digit assigned to the night service number thus producing a series of interruptions in the circuit of relay 300 which de-energizes in response thereto. At each retraction of its armature 315 a circuit is completed extending from ground by way of armature 315 and its back contact, armature 319 and its front contact, off normal springs 353 and 354, winding of the slow acting 95 series relay 302, and the winding of the vertical magnet 311 to battery. The above is the circuit over which the first vertical magnet impulse is sent. Upon the first vertical step of the shaft, the off normal springs are shifted and the impulses to the vertical magnet travel over a new path which includes the springs 353 and 355 and armature 324 and its front contact. The vertical magnet 311 operates to raise the switch wipers 360-362, inclusive, step by step until 100 they are placed opposite the level of bank contacts in which is situated the night service number. The slow acting relay 302, which is energized in series with the vertical magnet, maintains its armature attracted throughout 105 the vertical operation of the switch and at the termination of the vertical movement de-energizes transferring the operating circuit to the rotary magnet 312.

The watchman may now operate his calling device in accordance with the last digit 110 of the night service number. As before, the line relay 300 responds to the interruptions in its line circuit and at each retraction of 115 its armature completes a circuit extending as follows: ground by way of armature 315 and its back contact, armature 319 and its front contact, off normal springs 353 and 355, armature 324 and its back contact, normally closed springs controlled by relay 306, 120

armature 351 and its back contact, and, thence through the winding of the rotary magnet 312 to battery. Magnet 312 operates to rotate the switch wipers into engagement with the contact set associated with the night service number, which we will assume, is the bank contacts 379-381, inclusive. The springs 338 are cam springs adapted to be operated when the switch wipers are rotated into engagement with either the conference or night service number. A circuit is now completed extending from ground through the lower winding of relay 304, cam springs 338, and through the lower winding of the ring cut off relay 305 to battery. Relay 304, upon operating, places the impedance 303 across the talking conductors and relay 305 prepares a point in the talking connection. The slow acting relay 307 is energized in multiple with the rotary magnet and operates to connect the test wiper 361 to the test relay 306. The night number will of course be idle at this time as there is no necessity of it being used except by the watchman. Upon the deenergization of the slow acting relay 307, shortly after the termination of the rotary movement of the switch, a circuit is completed extending from ground on release trunk conductor 320 by way of armature 340 and its back contact, lower winding of the switching relay 308, back contact and armature 346, normally closed springs controlled by the switching relay 308, test wiper 361, test contact 380, conductor 129, and thence through winding of the relay 91 to battery. The switching relay 308 will energize over this circuit and upon operating, establishes a locking circuit for itself at armature 349 and at armatures 348 and 352 completes the talking connection. Relay 91 will be energized over the previously traced circuit and upon operating, opens the circuit of the bells 98, 99, and 100 at armature 92 and at armature 93 completes a circuit extending from ground by way of front contact and armature 93, sleeve of jack J^4 , sleeve of plug P^2 , sleeve of plug P^2 , sleeve of jack J' , release trunk conductor 136 to multiply connected test contacts in the banks of local connector selector repeaters, whereby the outgoing trunk line is prevented from being seized by any unrestricted branch exchange subscriber even if the operator at the main exchange should pull down the connection before the watchman hangs up his receiver. By the effacement of the supervisory signal L^{12} in the calling main exchange operator's cord circuit the operator will be informed that the night watchman has answered. Conversation may now be carried on between the calling subscriber at substation A^2 and the watchman at substation A. When it is terminated the night-watchman by hanging up the receiver at substation A releases the connector H' and

again lights the supervisory lamp L^{12} and upon the operator withdrawing the plug of her cord circuit from the jack J^1 all the apparatus is restored to its normal position.

Calls from the attendant at the private automatic exchange to the main exchange.

The attendant operator at the private automatic exchange may sometimes find it necessary to call the main exchange operator. In order to do this she will insert the plug of an idle cord circuit, which we will assume is the plug P of the cord circuit O' , into the jack of an idle trunk line extending to the main exchange and operate her calling out key K . When the plug P is inserted into the jack J^2 a circuit is completed over the sleeve of the cord for the relays 50 and 26 and the busy visual 29. Relay 26, upon operating, opens the circuit of the polarized relay 27 which relay retracts its armature into engagement with its associated contact either when the circuit of 27 is opened, or when the battery is reversed. By the insertion of the plug P into the jack J^2 the springs 71 are closed and when relay 27 retracts its armature a circuit is completed extending from ground by way of springs 71, armature 38 and its associated contact and thence through the winding of relay 28 to battery. Relay 28, upon energizing, places ground on the multiplied release trunk conductor 136 in the banks of selector connector repeaters thus rendering the trunk line busy in the usual manner. Relay 28 at armature 39 also prepares a point in the operating or signalling circuit of the lamp associated with this trunk line in the main exchanges.

It will be noted that the relay 28 is not energized and consequently the armature 39 is not attracted until the plug is fully inserted in the jack. This arrangement prevents any false operation of the line signal associated with the trunk line in the main exchange, should the operator plug in with her calling out key K thrown. Relay 50, upon energizing, operates in the same manner as before, and completes the circuit of the supervisory lamp L^6 . The relays 52 and 53 are now in bridge of the trunk conductors and relay 52 energizes thereby opening the circuit of relay 51. By the operation of the calling out key K these relays are deenergized but the relay 51 is not energized for the reason that a point in its circuit is broken at springs 77 of key K . Another result of the operation of the key K is that a circuit is completed extending from ground through spring 81 and its working contact, and through the winding of relay 80' to battery. Relay 80', upon energizing, prepares the signalling circuit for the main exchange operator. This circuit extends over the following path: from ground by way of back con-

tact and armature 610, trunk conductor 429, ring of the jack J^2 , ring of the plug P, spring 75 of key K and its working contact, right hand windings of the repeating coil, 5 armature 85 and its front contact, springs of the calling device S, springs of key K^2 , spring 82 and its working contact, tip of plug P, tip of jack J^2 , trunk conductor 428, armature 611 and its back contact, and 10 through the winding of the line relay 425 to battery. Relay 425 is energized over this circuit and completes a circuit at armature 612 for the line lamp L^{13} . When the main exchange operator notes the lighting of the 15 lamp L^{13} she will place the answering plug of an idle cord circuit into the jack J^{11} thereby completing the circuit for the cut off relay 426 over the sleeve of her cord. By throwing the listening key K^6 in the cord circuit 20 O which it will be assumed is the cord circuit used to answer this call, the main exchange operator will be able to communicate with the attendant operator in the private automatic exchange and ascertain what she 25 desires. After finding the number of the desired main exchange subscriber the operator will test the desired line to see if it is idle. If such be the case by then inserting the plug P^{11} into the jack of the desired local line 30 which we will assume is that of the substation A^2 , a circuit is completed for cut off relay 410 over the sleeve of the plug and also for the answering supervisory lamp L^{12} . When the ringing key K^6 is operated ringing 35 current is imposed on the line from the ringing generator in the usual manner. When the called subscriber answers the circuit is completed over the line for the supervisory control relay 421 which, upon operating, 40 short circuits the lamp L^{12} thereby notifying the operator that the call is being answered. Conversation may now take place between the attendant operator in the branch exchange and the called subscriber in the 45 main exchange, battery being supplied to the called subscriber from the windings of the repeating coil in the cord circuit O and to the attendant operator from the local battery associated with her headset. When the 50 conversation is terminated the called subscriber by replacing his receiver will light the associated supervisory lamp L^{12} , and upon the attendant operator withdrawing the plug P from the jack J^2 the lamp L^{11} is operated. The main exchange operator will 55 now withdraw the answering and calling plugs from the jacks J^{11} and J^{10} thereby restoring the apparatus to normal.

60 *Calls from the private automatic exchange subscribers to the manual main exchange.*

The private automatic exchange is also provided with what is known as a restricted service. In this arrangement only certain 65 subscribers are allowed to make outgoing

calls to the main exchange. This is accomplished by placing an extra wiper on all the line switches and those subscribers who are entitled to outgoing service have this extra wiper connected to ground. The manner in 70 which the system operates in this case will now be described.

For this purpose we will assume that the subscriber at substation A desires to make an outgoing call and it will be assumed further that he is a non-restricted subscriber. When the receiver is removed at substation A a circuit is completed for the line relay 260 of the line switch C. The line switch C will then operate as before described to extend its associated line to an idle connector switch which we will assume is the switch H' . The line relay 300 of the connector H' is energized over the line circuit and upon operating, completes a circuit of the slow 80 acting release relay 301. As before, the latter relay, upon energizing, prepares the circuits of the connector H' for operation at armature 319 and at armature 318 establishes a holding circuit for the line switch C, a 85 branch of this circuit also extending to multiply connected test contacts in the banks of the connector switches whereby the said line is protected from intrusion in the usual manner. 90

As the trunk lines leading to the main exchange terminate in the tenth level, the subscriber will operate his calling device in accordance with the digit O. Then interruptions are thereby produced in the line 100 circuit of relay 300 which operates to control the operation of the vertical magnet 311. Magnet 311 operates to raise the switch wipers 360-362, inclusive, opposite the tenth level of bank contacts. The springs 330-333 105 are shaft springs adapted to be actuated when the switch wipers are raised opposite the tenth level of bank contacts. This may be accomplished by any suitable cam arrangement. To continue, when the switch 110 wipers are raised to the tenth level the springs 330 and 332 are forced into engagement with their working contacts. By the operation of the spring 330 a circuit is completed extending from ground through the 115 lower winding of relay 304 by way of shaft controlled springs 330 and 331 and through the lower winding of the ring cut off relay 305 to battery. Upon energizing, relay 305 establishes a locking circuit for itself at 120 armature 336 and at armatures 335' and 337 prepares a point in the talking circuit. Relay 304, upon operating places the impedance coil 303 across the talking conductors of the switch H' . The relay 302, 125 which is energized in series with the vertical magnet, maintains its armature attracted for a short interval after the termination of the vertical movement of the switch. As soon as the springs 332 and 323 close, a cir- 130

cuit is completed from ground on discriminating trunk 321 by way of shaft controlled springs 332 and 333, springs 326 and 325, armature 323 and its front contact, back contact 5 and armature 343, and through the winding of the test relay 306 to battery. Upon energizing, relay 306 establishes a locking circuit for itself at armature 340 and at armature 341 prepares the rotary magnet 10 circuit. Upon the deenergization of the slow acting relay 302, a circuit is completed extending from ground on discriminating trunk 321 by way of shaft controlled springs 332 and 333, springs 326 and 325, armature 15 323 and its back contact, armature 341 and its front contact, armature 351 and its back contact, and through the winding of the rotary magnet 312 to battery. Magnet 312 operates to rotate the switch wipers into engagement 20 with the first set of contacts in the tenth level and to break the locking circuit of the test relay 306 which deenergizes opening the circuit of the rotary magnet which deenergizes also. The slow acting relay 307 25 is energized in multiple with the rotary magnet and operates as before, to connect the test wiper 361 to the test relay 306. The further operation of the switch depends upon whether or not the trunk line, with 30 which the switch wipers are in engagement, is busy or idle. If busy, there will be a ground potential present on the test contact engaged by test wiper 361. A circuit may then be traced extending from the said 35 grounded test contact by way of the test wiper 361, normally closed springs controlled by relay 308, armature 346 and its front contact, back contact and armature 343, and through the winding of the test 40 relay 306 to battery. Relay 306 will energize over this circuit to again complete the rotary magnet circuit. This alternate operation of the test relay 306 and the rotary magnet 312 will continue until an idle trunk 45 is found which, we will assume, is the trunk line associated with the bank contacts 370-372, inclusive. When this occurs there will be no ground potential present on the test contact 371 engaged by the test wiper 361. 50 No circuit will therefore be completed for the test relay 306. Then, following the deenergization of the slow acting relay 307, a circuit is completed extending from ground on the release trunk conductor 320 by way 55 of armature 340 and its back contact, lower winding of the switching relay 308, back contact and armature 346, normally closed springs controlled by armature 350, test wiper 361, test contact 371, conductor 136, 60 armature 40 and its back contact, and through the winding of relay 26 and the busy visual 29 to battery. The conductors 135-137, inclusive, shown in Fig. 4, extend to Fig. 3 where they are indicated by the 65 same reference numerals. They have not

been shown extending from one figure to the other in the drawings for the reason that their inclusion would complicate the circuits.

It will be seen that relays 308 and 26 are operated over the above traced circuit, relay 70 26, upon operating, opens the circuits of the polarized relay 27 at armature 36. The circuit of the polarized relay 27 being opened now at armature 36, armature 38 will be retracted into engagement with its associated 75 contacts, but this operation will have no function at this time. The busy visual, upon operating, serves to notify the attendant operator that this trunk line is in use. The switching relay 308 upon energizing, 80 establishes a locking circuit for itself at armature 349 and at armatures 348 and 352 completes a signalling circuit whereby the line signal L^{13} in front of the main exchange operator is lighted. The circuit by which 85 this is accomplished may be traced from battery through the winding of relay 425, by way of back contact and armature 611, trunk conductor 428, conductor 135, (Fig. 3), conductor 135 (Fig. 4), bank contact 372, wiper 90 362, front contact and armature 352, armature 337 and its front contact, front contact and armature 316, lower winding of the impedance coil 303, armature 335 and its front contact, front contact and armature 334, upper winding of the impedance coil 303, back contact and armature 345, front contact and armature 335', armature 348 and its front contact, wiper 360, bank contact 370, conductor 137 (Fig. 4), conductor 137 (Fig. 3), 100 trunk conductor 429, and thence by way of armature 610 and its back contact to ground. Relay 425 energizes over this circuit and at armature 435 completes the circuit of the line lamp L^{13} . This signal will serve to 105 notify the operator that a branch exchange subscriber desires to make a call and she will insert the plug of an idle cord circuit into the jack J^{11} , thereby extinguishing the lamp L^{13} and upon throwing her listening key 110 placing herself in communication with the calling subscriber. After ascertaining what number the calling subscriber wishes, the connection may be completed in accordance with well known manual practice as described hereinbefore. When the conversation is terminated the calling subscriber at 115 substation A by replacing his receiver upon the switchhook initiates the release of the switch H' in the usual manner. 120

Restricted service.

As before mentioned, the private automatic exchange is provided with what is known as restricted services whereby certain 125 subscribers only are allowed to make outgoing calls to the main exchange and to the second manual exchange, that is they are restricted from using certain levels of the local switches, namely, the ninth and tenth, 130

in which are terminated trunk lines extending to these two exchanges. The manner in which restricted service subscribers are discriminated against will now be explained.

- 5 For this purpose it will be assumed that the subscriber at substation A is restricted service subscriber. In this case armature 269 in the individual line switch C will not be connected to ground.
- 10 When the receiver is removed at substation A the line switch C operates to extend the line of the subscriber at substation A to an idle connector selector repeater which, we will assume, is the switch H'. Upon the 15 calling device at substation A being operated for the digit 0 the line relay 300 responds to the interruptions in its line circuit to control the operation of the vertical magnet 311. Magnet 311 operates to raise the 20 switch wipers step by step until they are placed opposite the tenth level. When this occurs the shaft controlled springs 330 and 332 are forced into engagement with their working contacts. As before, the slow acting 25 relay 302 is energized in series with the vertical magnet and maintains its armature attracted for a short interval after the termination of the vertical movement of the switch. In the present case there will be no 30 ground present on the discriminating trunk 321. By the operation of the shaft controlled springs 330 and 331 a circuit is completed extending from ground by way of the lower winding of relay 304, shaft controlled 35 springs 330 and 331, and through the lower winding of the ring cut off relay 305 to battery. Relays 304 and 305 operate over this circuit. Relay 305 upon energizing, establishes a locking circuit for itself at armature 40 336 and at armatures 335' and 337 prepares a point in the repeating circuits. Relay 304 upon attracting its armature places the impedance 303 in bridge of the talking conductors. When the springs 332 and 333 close a 45 circuit is completed extending from ground on release trunk conductor 320 through the resistance 304', shaft controlled springs 332 and 333, springs 326 and 325, armature 323 and its front contact, back contact and armature 50 343, and through the winding of the test relay 306 to battery. Relay 306 will energize in series with the upper winding of relay 304.
- Upon operating, relay 306 establishes a 55 locking circuit for itself at armature 340 and at armature 341 prepares the rotary magnet circuit. Following the deenergization of the slow acting relay 302 a short interval after the impulses to the vertical magnet have ceased a circuit may be traced extending from ground on release trunk conductor 320 by way of upper winding of relay 304, shaft controlled springs 332 and 333, springs 326 and 325, armature 323 and its 60 65 back contact, armature 341 and its front contact, armature 351 and its back contact, and through the winding of the rotary magnet 312 to battery. However, the rotary magnet will not operate in series with the resistance 304', as it does not receive enough current to energize. It will now be seen that a busy tone is placed on the lower talking conductor at armature 339, by the operation of the test relay 306. In this manner the subscriber at substation A is informed that he is not allowed outgoing service and upon replacing his receiver he will release the connector selector repeater H' as before described.
- It will be seen that by this discriminating feature only certain telephones are allowed to make out-going calls. At night this arrangement might be objectionable for the reason that the watchman may not be near a telephone that has outgoing service when he desires to make a call to the main exchange and hence unless special provision is made he would be unable to do so. In the present case, however, provision has been made to take care of this difficulty. The manner in which this is accomplished will now be described.
- Night calls to the main exchange by the watchman at the private automatic exchange.*
- In order to make outgoing call from any telephone the night watchman will be instructed to call the night service number that is ordinarily used for answering night calls. It will be assumed that the watchman is at substation A and that he proceeds to make a night call in this manner. When the receiver is removed at substation A individual line switch C operates as before described to select an idle connector selector repeater H'.
- When the calling device at substation A is operated for the first digit of the night service number a series of interruptions are produced in the circuit of the line relay 300. Relay 300 operating in response to these impulses controls the operation of the vertical magnet 311 in stepping the wipers opposite the level of bank contacts in which is located the night service number.
- The watchman may now operate his calling device for the final digit of the night service number. Now the line relay controls the operation of the rotary magnet 312 in rotating the wipers into engagement with the bank contacts assigned to night service which, we will assume, are the bank contacts 379-381, inclusive. All the above operations take place in a manner hereinbefore described. The slow acting relay 307 is energized in multiple with the rotary magnet and operates to connect the test wiper 361 to the test relay 306.
- It will be assumed that the night number

130

is idle when connection thereto is attempted. Under these circumstances there will be no ground present on the test contact 380 and no circuit will be completed for the test relay 306. Then, following the deenergization of the slow acting relay 307, a circuit may be traced extending from ground on release trunk conductor 320, by way of armature 340 and its back contact, lower winding of 10 the switching relay 308, back contact and armature 346, normally closed springs controlled by armature 350, test wiper 361, bank contact 380, conductor 129, and then through the winding of the relay 91 to battery. Relays 91 and 308 operate over this circuit. 15 Relay 91, upon energizing, removes the bells from across the trunk at armature 92 and at armature 93 completes a circuit extending over the following path: ground by way of 20 armature 93 and its front contact, sleeve of the jack J⁴, sleeve of the plug P³, sleeve of the plug P², sleeve of the jack J', where the circuit divides, one path extending to the 25 multiplied release trunk conductor 136 in the outgoing level of the banks of connector selector repeaters, and the other path extending by way of armature 40 and its back contact, through the winding of relay 26, and the winding of the busy visual 29 to battery. 30 Relay 26 operates to remove the ring up relay 25 from across the bridge of the trunk conductors 428 and 429 and also to open the circuit of the polarized relay 27. The latter relay immediately retracts its armature but 35 as ground is removed from its armature 38 by the operation of relay 26 this operation has no function at this time. The busy visual of course operates in the usual manner but as there is no attendant operator at 40 the position this operation is also without function. A circuit may now be traced extending from ground by way of back contact and armature 610, trunk conductor 429, ring of the jack J', ring of the plug P², ring 45 of plug P³, ring of jack J⁴, conductor 130, bank contact 381, wiper 362, front contact and armature 352, armature 337 and its front contact, front contact of armature 316 and the said armature, lower winding of the 50 impedance coil 303, armature 335 and its front contact, front contact and armature 334, upper winding of the impedance coil 303, back contact and armature 345, front contact and armature 335', armature 348 and its 55 front contact, wiper 360, bank contact 379, conductor 128, tip of jack J⁴, tip of plug P³, tip of the plug P², tip of the jack J', trunk conductor 428, armature 611 and its back contact, and through the winding of the 60 line relay 425 to battery. Relay 425, upon energizing, completes a circuit for the line lamp L¹³ before the operator in the manual exchange. When the main exchange operator notices the lighting of the lamp L¹³ 65 she will insert the answering end of an idle

cord circuit, such as the cord circuit O, into the jack J¹¹, thereby completing a circuit for the cut off relay 426 over the sleeve of her cord. Relay 426, upon operating, removes 70 normal battery and ground connections from the trunk connectors 428 and 429. It will be noticed that this circuit includes the answering supervisory lamp L¹¹, but as the circuit is completed at the same time for the supervisory control relay 420 which immediately 75 operates to short circuit the lamp L¹¹, the lamp will not remain lighted. In order to ascertain what number the branch exchange subscriber desires the operator will throw her listening key K⁵. The subsequent 80 operations by which the connection is extended to the desired local station and finally released will all take place in the usual manner.

Local calls between subscribers of the private automatic exchange.

The manner in which a local call is completed will now be described. For this purpose it will be assumed that the subscriber at substation A desires to call the subscriber at substation A'.

When the receiver is removed at the calling substation the line switch C operates in the usual manner to extend the line of its associated subscriber to an idle connector switch which, we will assume, is the connector H'. When the calling device is operated for the first digit of the desired number the line relay 300 in responding to the 95 interruptions in its line circuit controls the operation of the vertical magnet 311, which operates to raise the switch wipers 360-362, inclusive, step by step until they are placed 100 opposite the level of bank contacts in which 105 is located the desired subscriber's line.

When the impulse sender at the calling substation is operated in accordance with the final digit in the number of the desired subscriber at substation A' a series of interruptions 110 is again produced in the line circuit of the line relay 300. As before, relay 300 responds to these interruptions and at each retraction of its armature sends an impulse 115 of current to the rotary magnet 312 in multiple with the slow acting relay 307. Magnet 312 operates to rotate the switch wipers into engagement with the set of contacts associated with the line of the subscriber at substation A' which we will assume is the set 120 comprising bank contacts 389-391 inclusive. The slow acting relay 307 upon operating connects the test wiper to the test relay 306. If the line of the subscriber at substation A' is busy at this time there will be a ground 125 potential present on test contact 390 and a circuit will be completed for the test relay 306 which will energize and transmit the busy signal to the calling subscriber as described hereinbefore.

However, it will be assumed in the present case that the line of the subscriber at substation A' was idle at this time. Then, following the deenergization of the slow acting relay 307, a circuit is completed extending from ground on release trunk conductor 320 by way of armature 340 and its back contact, lower winding of the switching relay 308, back contact and armature 346, normally closed springs controlled by relay 308, test wiper 361, test contact 390, through the winding of the switching relay 225 of the line switch C' and the winding of the stepping magnet 227 to battery. Relays 308 and 225 operate over this circuit. Relay 225 only attracts its armature enough to disconnect the line of the substation A' from its normal battery and ground connections. Relay 308, upon operating, locks itself energized at armature 349 and at armatures 348 and 352 completes the ringing circuit of the subscriber at substation A'. Ringing current is then intermittently projected over the line of the called substation until an answer is obtained. When this occurs the circuit is completed for the ring cut off relay 305 which energizes and establishes a locking circuit for itself at armature 336 and at armatures 335' and 337 opens the ringing circuit and at the front contacts of these armatures finally completes the talking connection. Conversation may now take place between the calling and called subscriber over the heavy talking conductors, battery being supplied to the calling subscriber from the windings of the line relay 300 and battery being supplied to the called subscriber from the windings of the back bridge relay 303. When the conversation is terminated the release of the connector H' will take place upon the calling subscriber at substation A replacing his receiver upon the switchhook.

Calls from the private automatic exchange to the second manual exchange.

As before stated, the connector selector repeater H' also has access to ring down trunks going to the second manual exchange. The operation of the switch when this exchange is called will now be briefly described. For this purpose it will be assumed that the subscriber at substation A who is a non-restricted subscriber desires to call the second manual exchange. As the trunk lines leading to the second manual exchange terminate in the ninth level, the digit 9 will be called.

When the calling device is operated for the digit 9, the wipers of the selector connector repeater H' will be raised to the ninth level. By this operation the shaft controlled springs 332 and 333 are closed. As before, slow acting relay 302 is energized in series with the vertical magnet and, the shaft springs 332 and 333 being now closed, a circuit is completed at armature 323 for the

test relay 306. Upon the termination of the vertical movement of the switch, relay 302 deenergizes and a circuit is completed for the rotary magnet 312 in multiple with the slow acting relay 307. The trunk selecting operation will now take place in the same manner as hereinbefore described. The test relay 306 is energized each time the wipers engage a busy trunk line and operates to complete the rotary magnet circuit. When an idle trunk is found which, we will assume, is the trunk line terminating in bank contacts 375-377, inclusive, there will be no circuit for the test relay 306. A circuit is then effective following the deenergization of relay 307 extending from ground on release trunk conductor 320 by way of armature 340 and its back contact, through the lower winding of the switching relay 308 back contact and armature 346, normally closed springs controlled by relay 308, test wiper 361, test contact 376, and through resistance R' to battery. Relay 308 will operate over this circuit to establish a locking circuit for itself at armature 349 and at armatures 348 and 352 completing the ringing circuit.

The desired connection has now been established, ringing current is automatically projected out on the trunk line the same as in the case of a called local line and the ring down drop at the manual switchboard is operated in the usual manner. When the operator plugs in to answer the call the ring cut off relay 305 is operated. This relay operates to open the ringing circuit and to complete the talking connection. The connection to the desired station in this manual exchange may be completed by the operator through the medium of any suitable means which need not be explained herein.

Conference calls.

The private automatic exchange is also provided with a feature that is known as conference calling. This is an arrangement to enable three or more subscribers' lines to be telephonically connected together at the same time. The most common way of accomplishing this result is to have the subscriber that is setting up a conference call each party individually and inform him that a conference is to be held. At the predetermined time all the parties desired in the conference will call a special number. In order to enable the parties to connect with the same number the test contacts in the banks of the various local connector switches are not multiplied but instead the test contact associated with the conference number in each switch is connected to the locking winding of the switching relay.

In order to explain the operation of this conference feature it will be assumed that the subscriber at substation A desires to set up a conference. He will first remove his

receiver and in the usual manner call the various parties he desires in the conference, after which he will connect with the conference number. The local connections set up 5 by the subscriber at substation A will be substantially the same as the ones hereinbefore described and so it will only be necessary to explain the operation when the subscriber at substation A connects with the 10 conference number.

When the receiver is removed at the calling substation the individual line switch C operates in the usual manner to extend the calling subscriber's line into connection with 15 an idle local connector selector repeater. It will be assumed that the connector selector repeater H' was idle at this time and is selected for use by the line switch C.

The line relay 300 of the switch H' is energized over the calling subscriber's line loop 20 and in the usual manner closes the circuit of the slow acting release relay 301 which operates as before described to complete a holding circuit for the line switch C and to prepare the operating circuits of the connector H'.

When the calling device at substation A is operated for the first digit the line relay 300 responds to the interruptions in its line 25 circuit and controls the operation of the vertical magnet 311 in stepping the switch wipers opposite the level of bank contacts in which is located the bank contacts associated with the conference number. The slow acting 30 relay 302 is energized in series with the vertical magnet and maintains its armature attracted throughout the vertical movement 35 of the switch and at the termination thereof deenergizes and transfers the operating circuit to the rotary magnet 312.

The subscriber at substation A may now 40 operate his calling device in accordance with the last digit of the conference number. As before, the line relay retracts its armature 45 a plurality of times in response to the interruptions in its line circuit each time sending an impulse of current to the rotary magnet 312 in multiple with the slow acting relay 307. Magnet 312 operates to rotate the 50 switch wipers into engagement with the bank contacts associated with the conference number which, we will assume, are the bank contacts 384-386, inclusive. The slow acting relay 307 energizes and at its armature 55 346 connects the test wiper 361 to the test relay 306. However, as the test contacts of the conference number are not multiplied there will be no ground present on the test contact 385 and no circuit will be completed 60 for the test relay 306. When the switch wipers are rotated into engagement with the bank contact associated with the conference number a rotary cam on the switch shaft 65 forces the cam spring 338 into engagement with its working contact. A circuit is now

completed extending from ground through the lower winding of the relay 304, spring 338 and its working contact, and thence through the lower winding of the ring cut off relay 305 to battery. Relays 304 and 305 70 are energized over this circuit. Relay 304 operates to bridge the impedance coil 303 directly across the talking conductors and relay 305 operates to prepare a point in the talking connection. Then, following the de-energization of the slow acting relay 307, a circuit is completed for the switching relay 308 extending over the following path: from ground on release trunk conductor 320, by way of armature 340 and its back contact, lower winding of switching relay 308, back contact and armature 346, normally closed springs controlled by armature 350, test wiper 361, test contact 385, and thence through the upper winding of the switching relay 308 to battery. Relay 308 is energized over this circuit and upon operating, establishes a locking circuit for itself at armature 349 and at armatures 348 and 352 finally completes the talking connection. 80 It will be seen that the calling subscriber at 85 substation A is now in communication with all the other subscribers in the conference by way of the multiplied line conductors of the conference number, talking battery being supplied to each one from the windings of the line relay of the associated connector switch. When the conference is terminated the subscribers included therein, by replacing 90 their receivers upon the switchhooks, will initiate the release of their associated line and connector switches in the usual manner. In the operation above described 95 it will be seen that the test contact of the conference number in each connector switch 100 is connected to the locking winding of the switching relay in the associated connector switch. It will be apparent that by this construction it is unnecessary to connect a battery feed coil to each of these contacts as 105 was necessary heretofore and consequently a material saving is effected in the cost of installation.

Calls from the automatic main exchange to 115 the private automatic exchange.

It will now be assumed that the manual exchange has been cut over to automatic operation and the cut off relays of the individual line switches have been restored to their normal condition and the conductors leading to the manual equipment have been cut. In order to describe the operation of the invention in this case it will be assumed that the subscriber at substation A² desires 120 to call the private automatic exchange subscriber at substation A'. When the receiver is removed at the calling substation A² a circuit is completed for the line relay 451 125 of the individual line-switch C² over the 130

line conductors 401 and 402 in series. The line switch C² will now operate in the usual manner to select an idle trunk line extending to a first selector switch, which it will be assumed, is the selector E. When this occurs the switching relay 450 energizes and extends the calling subscriber's line to the line relay 470 of the selected selector E.

The line relay 470 energizes over the calling subscriber's line loop and at its armature 480 completes a circuit of the slow acting release relay 471. Upon energizing, the latter relay at armature 483 prepares the operating circuits of the selector E and at armature 482 places ground on release trunk conductor 484 thereby establishing a holding circuit which extends by way of test contact 465, test wiper 461, armature 454, through the winding of the switching relay 450 and thence through the winding of the stepping magnet 452 to battery. This holding circuit serves to maintain the switching relay in an operated position throughout the connections. A branch of the holding circuit also extends by way of the private normal conductor 458 to multiply connected test contacts in the banks of connector switches which have access to the line of substation A² whereby the said line is protected from intrusion in the well known manner.

The calling subscriber may now operate his calling device in accordance with the first digit of his desired number. By this operation a series of interruptions is produced in the circuit of the line relay 470 which retracts its armature a corresponding number of times in response thereto. At each retraction of its armature 480 a circuit is completed extending from ground by way of back contact and armature 491, armature 480 and its back contact, armature 483 and its front contact, winding of the slow acting series relay 472, and through the winding of the vertical magnet 477 to battery. Magnet 477 operates to raise the switch wipers 494-496, inclusive, step by step until they are placed opposite the desired level of bank contacts. The slow acting relay 472 is energized in series with the vertical magnet and upon the first vertical step of the shaft the off normal springs 478 close and a circuit is completed extending from ground on release trunk conductor 484 by way of armature 485 and its front contact, off normal springs 478 and thence through the winding of the interrupter relay 473 to battery. Upon energizing, the latter relay at armature 487 establishes a locking circuit for itself, and at armature 488 prepares the rotary magnet circuit. An instant after the termination of the vertical movement of the selector E the slow acting relay 472 is deenergized and a circuit is completed extending from ground on release trunk conductor 484 by way of

armature 485 and its back contact, armature 488 and its front contact, and through the winding of the rotary magnet 476 to battery. Magnet 476 operates to rotate the switch wipers into engagement with the terminals of the first trunk line in this level

and at armature 493 opens the locking circuit of the interrupter relay 473. The latter relay then deenergizes opening the circuit of the rotary magnet which deenergizes also. The operation of the selector E now depends upon whether the trunk line with which the switch wipers 494-496, inclusive, are associated is busy or idle. If busy, there will be a ground potential present on the test contact engaged by test wiper 495.

A circuit is then completed extending from the said grounded test contact by way of armature 490 and its back contact, back contact and armature 493, off normal springs 478, and through the winding of the interrupter relay 473 to battery. Relay 473 energizes over this circuit and operates in the same manner as before to establish a locking circuit for itself and to complete the rotary magnet circuit. As before, magnet 476 operates to rotate the switch wipers another step into engagement with the next trunk in the selected level and at the same time to break the locking circuit of the interrupter relay 473 which relay deenergizes breaking the rotary magnet circuit which deenergizes also. The alternate operation of the interrupter relay 473 and the rotary magnet 476 will continue until an idle trunk line is found, which, it will be assumed, is the trunk line comprising conductors 500-502 and terminating in bank contacts 497-499, inclusive. When this occurs there will be no ground potential present on the test contact 498 engaged by the test wiper 495. The switching relay 474 which has heretofore been short circuited by ground on various test contacts will energize over a circuit extending from ground on release trunk conductor 484, through the winding of the switching relay 474, back contact and armature 493, off normal springs 478, and through the winding of the interrupter relay 473 to battery.

It may be stated at this point that the switching relay 474 is of comparatively high resistance so as to prevent the energization of the interrupter relay 473 in series with it. Upon energizing, the switching relay 474 disconnects the incoming line conductors from the windings of the line relay and extends them by way of armatures 489 and 492, wipers 494 and 496, bank contacts 497 and 499, trunk conductors 500 and 502, normally closed springs controlled by relay 510, upper and lower windings of the line relay 511 of the connector H² to battery.

The line relay 511 is energized over the calling subscriber's line loop and closes the circuit of the slow acting release relay 512

at armature 535. Upon energizing, the latter relay at armature 538 prepares the circuits of the connector H^2 for operation and at armature 537 places ground on release 5 trunk conductor 501 thereby establishing a holding circuit which extends by way of test contact 498, test wiper 495, armature 490 and its front contact, at which point it divides one circuit extending through the 10 winding of the switching relay 474 of the selector E, the other extending back to switching relay 450 of the line switch C. This holding circuit serves to maintain the line switch C² and selector E in an operated 15 position.

The calling subscriber may now operate his calling device in accordance with the next digit of the subscriber's number at substation A'. A series of interruptions are 20 thus produced in the circuit of the line relay 511 which retracts its armature a plurality of times in response thereto. At each retraction of its armature a circuit is completed extending from ground by way of 25 armature 535 and its back contact, armature 538 and its front contact, off normal springs 541 and 540, winding of the vertical magnet 519, and through the winding of the slow acting series relay 514 to battery. The above 30 is the circuit over which the first vertical impulse is transmitted. Upon the first vertical step of the shaft, the off normal springs are shifted and the remaining impulses to the vertical magnet traverse a new circuit 35 which is the same as the one previously traced except that it includes the off normal springs 541 and 542 and armature 549 and its front contact (relay 514 being now in an operated position). The vertical magnet 40 519 operates to raise the switch wipers 580-583, inclusive, step by step until they are placed opposite the level of bank contacts in which is located trunk lines going to the private automatic exchange. The 45 slow acting relay 514 is energized in series with the vertical magnet and maintains its armatures attracted throughout the vertical movement of the switch and at the termination thereof deenergizes and transfers the 50 operating circuit to the rotary magnet 521.

The calling subscriber may now call the next digit of his desired number. As before, a series of interruptions is produced in the line circuit of the relay 511 which retracts its armature a corresponding number 55 of times. At each retraction of its armature an impulse of current is sent to the rotary magnet 521 over the following path: ground by way of armature 535 and its back contact, 60 armature 538 and its front contact, off normal springs 541 and 542, armature 549 and its back contact, back contact and armature 559, winding of the slow acting series relay 517, armature 573 and its back contact, and 65 thence through the winding of the rotary

magnet 521 to battery. Magnet 521 operates to rotate the switch wipers 580-583, inclusive, into engagement with the first trunk line leading to the private automatic exchange. The slow acting relay 517 is energized in series with the rotary magnet and operates to connect test wiper 581 to the test relay 516. The operation of the switch now depends upon whether or not the trunk line with which the wipers are associated 70 is busy or idle.

Where there are a number of trunk lines extending to a private automatic branch exchange the connector H^2 must be able to connect with the first idle trunk line extending to such an exchange or if all trunks are busy to return the busy signal to the calling subscriber. In order to arrange the connector H^2 to give this class of service two test wipers are provided. In order to enable the switch to rotate over busy lines the test contacts engaged by the test wipers must be tied together and those of the last trunk line in the group are left open. 80

Returning now to the operation of the connector H^2 when engagement is made with the first trunk line leading to the private automatic exchange. Supposing this trunk line to be busy a ground potential will be present on test contacts engaged by the test wipers 581 and 582. A circuit is then completed extending from the grounded test contact engaged by wiper 581 by way of the said test wiper, armature 564 and its front contact, armature 574 and its back contact, and through the winding of the test relay 516 to battery. Relay 516 operates over this circuit establishing a locking circuit for itself at armature 558 and preparing the circuit for interrupter relay 513. When the slow acting series relay 517 is deenergized a circuit is completed from the grounded test contact engaged by the test wiper 582, by way of the said test wiper, armature 563 and its back contact, back contact and armature 570, back contact and armature 567, armature 560 and its front contact, through the winding of the interrupter relay 513, and thence through the winding of the slow acting relay 514 to battery. Upon energizing, relay 513 at armature 546 establishes a locking circuit for itself, and at armature 545 completes the rotary magnet circuit. Magnet 521 operates to rotate the switch wipers into engagement with the second trunk line leading to the private automatic exchange and to break the locking circuit of the interrupter relay 513. The latter relay deenergizes breaking the circuit of the rotary magnet which de-energizes also. The slow acting relay 514 which is energized in series with the stepping relay operates to maintain the test wiper 581 in connection with the test relay 516. If this trunk line should also be busy, 110 115 120 125 130

ground will be present on the test contact engaged by wiper 581, the test relay 516 will be maintained energized, and the stepping relay 513 will again operate to close the rotary magnet circuit. The alternate operation of the stepping relay 513 and the rotary magnet 521 will continue until an idle trunk is found, or the switch wipers are rotated into engagement with the last 5 trunk line of the group which is also busy.

In this latter case, the test contacts engaged by the test wipers 581 and 582 are not connected and ground will only be present on the test contact engaged by the test 10 wiper 581. No circuit will therefore be completed for stepping relay 513 but the test relay 516 will be maintained operated. The busy tone is then placed on the calling subscriber's line at armature 561. The subscriber at substation A² upon hearing this tone, will know that all the trunk lines extending to the private automatic exchange are busy and he will therefore replace his receiver upon the switchhook thereby releasing the switches H², E and C² in the usual manner.

It will now be assumed that an idle trunk line was found extending to the private automatic exchange which trunk line terminates in the bank contacts 585-588, inclusive. When the switch wipers are rotated into engagement with this set of contacts, there being no ground present on test contact 586, no circuit will be completed for the test 20 relay 516. Then, following the deenergization of the slow acting relay 517, a circuit is completed extending from ground on release trunk conductor 501, armature 558 and its back contact, lower winding of the switching relay 518, back contact and armature 564, test wiper 581, test contact 586, winding of the switching relay 600 of the line switch C³ and thence through the winding of the stepping magnet 601 to battery.

Relays 518 and 600 operate over this circuit. However, due to a mechanical interlocking device controlled by the armature of the line relay 602, which is now normal, the switching relay is only operated enough to 30 disconnect the trunk conductors 428 and 429 from their normal battery and ground connections in the line switch C³. Relay 518, upon operation, establishes a locking circuit for itself at armature 571 and at armatures 569 and 575 completes the ringing circuit. The operation of the relay 600 in the line switch C³ as before stated, removes the normal battery connections from the trunk line comprising conductors 428 and 429. The polarized relay 27 which is bridged across the trunk line in the private automatic exchange will therefore retract its armature thereby completing the circuit of the slow acting relay 28. Upon energizing, the latter relay at armature 40 places 40 ground on the release trunk conductor 136 which extends to multiply connected test contacts in the banks of selector connector repeaters in the private automatic exchange which have access to this trunk line. By 45 the energization of the relay 518 ringing current is projected over the trunk line by the connector H² over a circuit extending from the ungrounded pole of generator V, upper winding of the ring cut off relay 515, back contact and armature 551, armature 569 and its front contact, wiper 580, bank contact 585, trunk conductor 429, back contact and armature 36, through the winding of the ring up relay 25, springs of the jack 50 J', trunk conductor 428, bank contact 588, wiper 583, front contact and armature 575, and armature 555 and its back contact to ground. The ring up relay 25 is immediately energized over this circuit and, in 55 operating, short circuits the condenser normally included in its circuit at armature 33, thereby providing a direct current path across the trunk conductors, at armature 35 establishes a locking circuit for itself 60 and at armature 31 lights the line lamp L' before the attendant operator. A path for direct current having now been provided across the trunk conductors 428 and 429 the ring cut off relay 515 in the connector H² 65 will be energized. Upon operating, this relay at armature 553 establishes a locking circuit for itself and at armatures 551 and 555 places the battery supply from the windings of the back bridge relay 510 across 70 the trunk conductors. The back bridge relay 510 will not, however, be energized at this time as the lower winding of relay 25 is of sufficiently high resistance to prevent its operation at this time. It should be 75 noted that current flows in the same direction in both windings of relay 25 at this time by reason of the fact that the battery supplied by relay 510 is of the reverse polarity to that normally on the trunk when the 80 trunk is idle. For this same reason the polarized relay 27 will remain deenergized during the above operations. However, should the calling subscriber receive no answer from the attendant operator he will 85 replace his receiver thereby causing the deenergization of the line relay 511 of the connector H². By the latter operation the circuit of the slow acting release relay 512 is opened and it will deenergize after a short 90 interval. A circuit is then completed for the release magnet 520 of the connector switch (relay 510 being in an inoperative position). Immediately upon the release of the connector, the normal battery supplied 95 to the trunk by the line switch C³ is replaced but as this is of the opposite polarity to that supplied by the connector H² the current flowing in the lower winding of relay 25 will be reversed and as the magnetic 100

field set up by the two windings of relay 25 now oppose each other this relay will de-energize. It will be understood of course that the armatures 32 and 33 of the relay 5 25 break their contacts simultaneously. By the deenergization of relay 25 the line signal L' is effaced.

It will now be assumed that the attendant operator was at her position when the call 10 was made. Upon the attendant operator noticing the lighting of the line lamp L' , she will insert the plug of an idle cord circuit into the jack J^2 . It will be assumed that she selects cord circuit O' , which is idle 15 at this time, for use. When the plug P is placed in jack J^2 a circuit is completed over the sleeve of the plug for the cut off relay 26 and the busy visual 29 in multiple, ground being supplied to the sleeve of the plug 20 through the winding of relay 50. Relay 26, upon operating, opens both the locking circuits of the ring up relay 25 which relay de-energizes thereby extinguishing the line lamp L' . Relay 26 also upon energizing at 25 armature 34 opens a point in the circuit of the slow acting relay 28. But this will be ineffective at this time for the reason that when the plug is shoved into the jack J^2 the springs 71 are closed. The relay 50, which 30 is energized over the sleeve of the plug P , at its armature 60 completes a circuit extending from ground by way of front contact and armature 60, springs 77, armature 71' and its back contact, and through the lamp 35 L^6 to battery. By the insertion of the plug P into the jack J^2 , the relays 52 and 53 are placed in bridge across the trunk conductors. Owing to the high resistance of the winding of relay 52, relay 52 is energized over this 40 circuit but the back bridge relay 510 is not operated. The operation of relay 52 serves to open a point in the energizing circuit of relay 51. In order to communicate with the calling subscriber and ascertain what number 45 he desires the operator will throw her listening key K' thereby associating her head set with the cord circuit. When the key K' is operated the high resistance relay 52 is short circuited and restores and the relays 53 and 54 are energized. Relay 53, 50 upon operating, establishes an additional shunt around the relay 52 so that when the key K' is restored the relay 52 will remain deenergized and relay 54, upon energizing, 55 maintains the circuit of relay 51 opened. As soon as the high resistance relay 52 is short circuited sufficient current will flow over the trunk line to operate the back bridge relay 510 of the connector H^2 . Relay 60 510 upon energizing reverses the current flow in the line of the calling subscriber for any desirable purpose. When the operator ascertains what number the subscriber desires she will insert the plug P' into the jack of an idle trunk line extending to an incoming

connector switch. It will be assumed that jack J^3 is idle at this time and was selected for use by the operator. A circuit is thereby completed extending from ground by way of normally closed springs controlled by armature 85, springs of the calling device S , springs of the key K^2 , spring 79 and its working contact, sleeve of the plug P' , sleeve of the jack J^3 , spring 80 and its working contact, conductor 126, and through the 70 winding of the line relay 150 of the connector H , Fig. 4, to battery. 75

The attendant operator may now operate her calling device for the digits of the local subscriber's number. The operation of the connector H has been described hereinbefore and will be readily apparent by reference to that explanation. When the called subscriber at substation A' answers, the supervisory control relay 55 in the attendant operator's cord circuit O' is operated and the lamp L^6 extinguished. The operator will thus be notified that the subscriber at substation A' has answered. The operation of relay 55 also opens the formerly traced circuit extending through relays 53 and 54. Relay 53 deenergizes, but relay 54 remains operated over the new circuit completed over the trunk by the response of the called subscriber at station A' . Conversation may now take place between the calling and called subscribers. When this is terminated both subscribers will replace their receivers upon their respective switchhooks. When the receiver is replaced at the substation A' the relays 54 and 55 in the cord circuit O are de-energized and the lamp L^6 lighted. The de-energization of relay 55 again completes the bridge including relays 52, 53, and 54, and relay 52 again operates to open its contacts 85 90 before the armature 72 of relay 54 has restored, to prevent the operation of relay 51 at this time. When the receiver is replaced at the calling substation A^2 the line relay 511 of the connector H^2 is deenergized and the 95 circuit of the slow acting release relay 512 is opened. Before the deenergization of relay 512 an impulse of current is sent over the following path: ground by way of armature 535 and its back contact, armature 538 and its front contact, armature 554 and its front contact, armature 551 and its front contact, and thence through the upper winding of the back bridge relay 510 to battery. Battery is thus momentarily shunted from the 100 trunk conductor 428 and the relay 52 in the cord circuit O' is momentarily restored to normal. A circuit is now effective extending from ground by way of front contact and armature 60, springs 77, back contact and armature 66, armature 64 and its back contact, armature 72 and its back contact, normally closed springs controlled by armature 61, and thence through the upper winding of relay 51 to battery. Upon energizing, relay 105 110 115 120 125 130

51 establishes a locking circuit for itself at armature 61, at armature 62 places its lower winding in bridge across the talking conductors in order to prevent the release of the 5 connector H^2 and at armature 63 lights the calling supervisory signal L^5 . The connector H^2 is not released at this time as its back bridge relay 510 is still energized and the circuit for the release magnet 520 is 10 maintained opened at armature 533. Upon the deenergization of relay 512, battery is again replaced on the trunk conductors 428 and 429 and the relay 52 in the cord circuit O' is again energized. When relay 512 in 15 the connector H^2 deenergizes ground is removed from the release trunk conductor 501 and the selector E and line switch C are accordingly released.

By the operation of the supervisory signals L^5 and L^6 , the attendant operator will 20 know that the conversation is completed and she will withdraw the plugs of the cord circuit O' from the jacks J^2 and J^3 thereby releasing the connector H in the branch exchange and the connector H^2 in the main exchange in the usual manner.

Had the calling subscriber at substation A^2 replaced his receiver upon the switch-hook before the called subscriber, battery 25 would have been momentarily removed from the trunk conductors 428 and 429 the relay 51 in the cord circuit O' would be energized and the calling supervisory lamp L^5 lighted in the same manner as hereinbefore described. 30 When the called subscriber hangs up, the lamp L^6 will be lighted. The operator will be notified by these operations that conversation is terminated and will withdraw the plugs of the cord circuit from the associated 35 jacks thereby releasing the connector H^2 in the main exchange and restoring all the apparatus to normal.

Calls from the automatic main exchange to 45 the private automatic exchange via the night service connection.

It will now be assumed that the subscriber 50 at A^2 calls the branch exchange at night when the attendant operator thereat is off duty. Under these conditions the night cord circuit O^2 will have been placed in the jacks J' and J^4 . When the receiver is removed at substation A^2 the line switch C^2 55 operates in the manner hereinbefore described to select an idle trunk line extending to a selector which it will be assumed is the selector E. Immediately upon the extension of the line, the line and release relays 470 60 and 471 of the selector E are energized in the same manner as before and with the same results.

When the calling device is operated for 65 the first digit of the private automatic exchange number a series of interruptions is

produced in the circuit of the line relay 470 which retracts its armature a corresponding number of times. By the operation of the line relay 470 the vertical magnet is caused to raise the wipers step by step until they 70 are placed opposite the desired level of bank contacts. The slow acting series relay 472 is energized in series with the vertical magnet and maintains its armature attracted throughout the vertical movement of the 75 switch. Upon the first vertical step of the switch a circuit is completed for the interrupter relay 473 which operates to establish a locking circuit for itself and prepare the circuit of the rotary magnet. Upon the termination of the vertical movement, the slow acting relay 472 deenergizes and completes a circuit of the rotary magnet which operates to rotate the switch wipers into engagement with the first trunk line of the selected level and to break the locking circuit of the interrupter 473. Relay 473, then de-energizes breaking the circuit of the rotary magnet 476 which deenergizes also. If the first trunk line in the selected level is busy, 80 there will be a ground present on the test contact engaged by the test wiper 495. The interrupter relay 473 will be again energized to complete the rotary magnet circuit which will operate in the same manner as before. 85 The alternate operation of the interrupter relay 473 and the rotary magnet 476 will continue until an idle trunk is found which, we will assume, is the trunk line terminating in the bank contacts 497 and 499, inclusive. When this occurs there will be no ground present on the test contact engaged by test wiper 495, the switching relay 474 being no longer short circuited will energize in series with the interrupter relay 473. 90 Upon energizing, relay 474 at armatures 489 and 492 extends the incoming line conductors by way of wipers 494 and 496, bank contacts 497 and 499, trunk conductors 500 and 502, normally closed springs controlled by armatures 531 and 532 to the upper and lower windings of the line relay 511 of the connector H^2 to battery.

The line relay 511 is energized over the calling subscriber's line loop and operates 115 to complete the circuit of the slow acting release relay 512. The latter relay operates in the usual manner to prepare the circuits of the connector H^2 for operation at armature 538, and at armature 537 places ground 120 on the release trunk 501 thereby establishing a holding circuit for the switching relay 450 of the line switch C^2 and the switching relay 474 of the selector E.

The subscriber at substation A^2 may now 125 operate his calling device for the next digit of the desired number. A series of interruptions are produced in the line circuit of the relay 511 which deenergizes a corresponding number of times. At each retraction of its 130

armature 535, a circuit is completed for the vertical magnet 519 in series with the slow acting relay 514. Magnet 519 operates to raise the switch wipers step by step until they are placed opposite the level of bank contacts in which are terminated trunk lines leading to the private automatic exchange. The slow acting relay 514 is energized in series with the vertical magnet and maintains its armatures attracted throughout the vertical operation of the switch and at its termination deenergizes transferring the operating circuit to the rotary magnet 521.

15 The calling subscriber at substation A² may now call the third and final digit of the private automatic exchange number. As before, a series of interruptions is produced in the circuit of the line relay 511 which retracts its armature a plurality of times in response thereto. At each retraction of its armature 535, a circuit is completed for the rotary magnet 521 in series with the slow acting relay 517. The rotary magnet 521 operates to rotate the switch wipers 580-585, inclusive, into engagement with the set of bank contacts associated with the first trunk line in the group of trunk lines extending to the private automatic exchange which, we 20 will assume, are the bank contacts 585-588, inclusive. The slow acting relay 517 upon energizing, connects the test wiper 581 to the test relay 516. Should this trunk line happen to be busy ground will be present on both test contacts 586 and 587, test relay 516 will be energized, and also the interrupter or stepping relay 513, as there is ground present on both test contacts engaged by test wipers 581 and 582. The latter relay, upon 25 energizing, closes a locking circuit for itself at armature 546 and at armature 545 completes a circuit of the rotary magnet. The rotary magnet operates to rotate the switch wipers into engagement with the contacts associated with the next trunk line. As before, the alternate operation of relay 513 and the rotary magnet 521 will continue until an 30 idle trunk is found.

However, it will be assumed in the present 35 case that the trunk line terminating in the bank contacts 585-588, inclusive, was idle when the switch H² was operated into connection therewith. Under these conditions there will be no ground present upon the test contact engaged by the test wiper 581, no circuit will be completed for the test relay 516. Then, following the deenergization of the slow acting relay 517, a circuit may be traced 40 extending from ground on the release trunk conductor 501 by way of normally closed springs controlled by armature 548, armature 558 and its back contact, lower winding of the switching relay 518, back contact and armature 564, test wiper 581, test contact

586, winding of the switching relay 600 of 65 the line switch C³ and thence through the winding of the stepping magnet 601 to battery. Relays 600 and 518 are operated over this circuit. However, due to a mechanical interlocking device controlled by the armature of the line relay 602, relay 600 upon operating, only attracts its armatures far enough to clear the trunk conductors 428 and 429 from their normal battery and ground connections in the line switch C³. Relay 70 518, upon operating closes a locking circuit for itself at armature 571 and at armatures 569 and 575 completes the ringing circuit. Ringing current is then intermittently projected over a circuit extending from the ungrounded pole of generator V through the upper winding of the ring cut off relay 515, back contact and armature 551, armature 569 and its front contact, wiper 580, bank contact 585, trunk conductor 429, ring of the 75 night jack J', ring of the plug P², ring of the plug P³, the bells 100, 99 and 98 in multiple, through the condenser, tip of the jack J⁴, tip of the plug P³, tip of the plug P², tip of the jack J', trunk conductor 428, bank 80 contact 588, wiper 583, front contact and armature 575, and armature 555 and its back contact to ground. The bells 98, 99 and 100 are intermittently operated over the above 85 traced circuit in the same manner as herein- 90 before described.

The operations by which the night watchman establishes a connection with the incoming call takes place in identically the 100 same manner as was described when a call was made at night and when the main exchange was operating manually, and hence will be readily understood. It will be apparent of course that as soon as the watchman connects with the night service number 105 the ring cut off relay 515 in the connector H² will be immediately energized and will operate to cut off the ringing current and complete the talking connection. After the 110 conversation between the calling subscriber at substation A² and the night watchman in the private automatic exchange is terminated, the subscriber at substation A², by replacing his receiver upon the switchhook, will initiate the release of the switches H², E 115 and C². The night watchman in the private automatic exchange, by replacing the receiver at his substation, will cause the release of the operated switches in the branch 120 exchange, all the foregoing operations taking place in the manner hereinbefore described.

Local calls between subscribers of the automatic main exchange.

In order to describe the operation of the switches in the main exchange when one main exchange subscriber calls the other, it

will be assumed that the subscriber at substation A² desires to call the subscriber at substation A³.

When the receiver is removed at substation A² the line switch C² operates in the usual manner to extend the calling subscriber's line to an idle first selector switch which, we will assume, is the selector E. The line and release relays 470 and 471 are energized over the line circuit and operate in the same manner as before.

When the calling device at substation A² is operated for the first digit of the desired subscriber's number a series of interruptions are produced in the circuit of the line relay 470 of the selector E. At each retraction of its armature 480 the line relay sends an impulse of current to the vertical magnet 477 in series with the slow acting relay 472. The vertical magnet 477 operates to raise the switch wipers step by step until they are placed opposite the desired level of bank contacts. The slow acting relay 472 is energized in series with the vertical magnet and upon the first vertical step of the switch closes at its armature 485 a circuit for the interrupter relay 473. The latter relay upon energizing, establishes a locking circuit for itself and prepares a point in the rotary magnet circuit. Upon the termination of the vertical movement of the switch, the slow acting relay 472 deenergizes and completes the rotary magnet circuit. Magnet 476 operates to rotate the switch wipers into engagement with the first trunk line in the selected level and to open the locking circuit of the interrupter relay 473 which de-energizes breaking the circuit of the rotary magnet which deenergizes also. If the trunk line with which the switch wipers are now associated should happen to be busy, there will be a ground potential present on the test contact engaged by the test wiper 495. The interrupter relay 473 will be again energized and will operate to close the rotary magnet circuit. The alternate operation of the interrupter relay and the rotary magnet will continue until an idle trunk is found which, we will assume, is the trunk line terminating in bank contacts 497-499, inclusive. When this occurs there will be no ground present on the test contact engaged by the test wiper 495, the switching relay 474 being no longer short circuited will energize in series with the interrupter relay 473. Upon operating, relay 474 disconnects the incoming line conductors from the windings of the line relay 470 and extends them by way of armatures 489 and 492, wipers 494 and 495, bank contacts 497 and 499, trunk conductors 500 and 502, normally closed springs controlled by armatures 531 and 532, to the upper and lower windings of the line relay 511 of the connector H². The line relay 511 is energized over the

calling subscriber's line loop and closes the circuit of the slow acting release relay 512. The latter relay, upon operating, prepares the circuits of the connector H² for operation at armature 538 and at armature 537 places ground on release trunk conductor 501 thereby establishing a holding circuit for the line switch C² and the selector E.

The calling subscriber may now operate his calling device in accordance with the second digit in the desired number. A series of interruptions is produced in the circuit of the line relay 511 which retracts its armature 535 a corresponding number of times. At each retraction of its armature 535, an impulse of current is sent to the vertical magnet 519 in series with the slow acting relay 514. Magnet 519 raises the switch wipers step by step until they are placed opposite the level of bank contacts in which is located the contact set associated with the substation A³. The slow acting relay 514 is energized in series with the vertical magnet and maintains its armatures attracted throughout the vertical operation of the switch and at its termination deenergizes and transfers the operating circuit to the rotary magnet 521.

The calling subscriber may now operate his calling device in accordance with the third final digit in his desired number. As before, a series of interruptions are produced in the circuit of the line relay 511 which operates in response thereto. At each retraction of its armature 535, an impulse of current is sent to the rotary magnet 521 in series with the slow acting relay 517. Magnet 521 operates to rotate the switch wipers 580-583, inclusive, into engagement with the set of bank contacts associated with the line of the substation A³, which, we will assume, is the bank contacts 595-598, inclusive. The slow acting relay 517 which is energized in series with the rotary magnet operates to connect the test wiper 581 to the test relay 516. Should the line of the substation A³ be busy at this time there will be a ground potential present on the test contact engaged by the test wiper 581 and a circuit will be completed for the test relay 516. Upon energizing, relay 516 at armature 558 establishes a locking circuit for itself and at armature 561 places the busy tone on the lower heavy talking conductor. The calling subscriber at substation A² upon hearing this tone will replace his receiver upon the switchhook thereby releasing the connector H², selector E, and the line switch C².

However, it will be assumed in the present case that the line of the subscriber at substation A³ was idle when the connector H² attempted to connect therewith. Under these circumstances, there will be no ground present on the test contact 596 and the test relay 516 will not be energized. Then, fol-

lowing the deenergization of the slow acting relay 517, a circuit is completed extending from ground on release trunk conductor 501 by way of armature 558 and its back contact, 5 lower winding of the switching relay 518, back contact and armature 564, test wiper 581, test contact 596 and through the winding of the switching relay and the motor magnet of the line switch C⁴ to battery. It 10 will be understood that the line switch C⁴ is similar to the line switch C² and in order to facilitate the description the line switch C⁴ has only been indicated diagrammatically. The switching relay 518 of the connector H², 15 is energized over the above circuit and upon operating, establishes a locking circuit for itself at armature 571 and at armatures 569 and 575 completes the ringing circuit. Ringing current is then intermittently projected 20 over the line of the subscriber at substation A³ until an answer is obtained. When this occurs a circuit is completed for the ring cut off relay 515 which energizes over the called subscriber's line loop. Upon operating, 25 relay 515 establishes a locking circuit for itself at armature 553 and at armatures 551 and 555 opens the ringing circuit and at the front contacts of these armatures finally completes the talking connection. Conversation 30 may now take place between the subscriber at substation A² and the subscriber at substation A³, battery being supplied to the calling subscriber from the windings of the line relay 511 and to the called subscriber 35 from the windings of the back bridge relay 510. When the conversation is completed the release of the connector H, the selector E, and the line switch C² will take place upon both subscribers replacing their receivers upon the switchhook. 40

Calls from the private automatic exchange to the main automatic exchange by non-restricted subscribers.

45 The manner in which an outgoing call is made from the private automatic exchange to the main automatic exchange will now be explained. As the operations of the switches in the branch exchange have been described 50 hereinbefore, it will be assumed that the subscriber at substation A has removed his receiver and operated a connector switch H' into engagement with the bank contacts 370-372, inclusive, which are terminals of an 55 outgoing trunk line. When this occurs the busy visual 29 is operated and also the relay 26 in multiple therewith. A circuit may now be traced extending from ground by way of back contact and armature 625, trunk 60 conductor 429, conductor 137, Fig. 3, conductor 137, Fig. 4, bank contact 370, wiper 360, front contact and armature 348, armature 335' and its front contact, armature 345 and its back contact, upper winding of the impedance coil 303, armature 334 and its front 65

contact, front contact and armature 335, lower winding of the impedance coil 303, armature 316 and its front contact, front contact and armature 337, armature 352 and its front contact, wiper 362, bank contact 70 372, conductor 135, Fig. 4, conductor 135, Fig. 3, trunk conductor 428, armature 626 and its back contact, and thence through the winding of the slow acting line relay 602 of the line switch C³ to battery. The line 75 relay 602 is energized over this circuit and causes the line switch C³ to select an idle trunk leading to a first selector. When the calling device at substation A is 80 operated a series of interruptions are produced in the circuit of the line relay 300 of the connector selector repeater H'. These interruptions are then repeated to the line relay of the first selector in the main exchange at armature 316 and the call will be 85 extended to a subscriber in the main exchange in the well known automatic manner. When the conversation is terminated the calling subscriber at substation A in the 90 private automatic exchange by replacing his receiver upon the switchhook will cause the release of the connector selector repeater H' and also that of the operated switches in the main automatic exchange. 95

Calls from the private automatic exchange to the main automatic exchange by the night watchman.

The above operations of the line switch C³ take place whenever the trunk line comprising conductors 428 and 429 is seized in the branch exchange either by a non-restricted subscriber or by the night watchman. The former connection has been described above and from this explanation the operations which take place when the trunk line is seized by the night watchman will be readily understood in conjunction with the following brief description. For this purpose it will be assumed that the night watchman 105 desires to make an outgoing call at night from the substation A. 110

When the receiver is removed at the calling substation the individual line switch C operates in the usual manner to select an idle trunk line and thereafter extend the associated line conductors to the line relay of the selector connector switch which we will assume in the present case is the connector H'. The line and release relays 300 and 301, respectively, are energized in the usual manner and operate as before described. 115 120 125

When the calling device at substation A is operated for the first digit of the night service number a series of interruptions is produced in the circuit of the line relay 300 which deenergize a corresponding number of times. At each deenergization, an impulse of current is sent to the vertical magnet 311 in series with the slow acting relay 130

302. The vertical magnet 311 operates to raise the switch wipers 360-362, inclusive, step by step until they are placed opposite the level of bank contacts in which is terminated the contact set associated with the night service number. The slow acting relay 302 is energized in series with the vertical magnet and maintains its armature attracted during the vertical movement of the switch and at the termination thereof deenergizes and transfers the operating circuit to the rotary magnet 312.

When the calling device at substation A is operated for the last digit of the night service number a series of interruptions are again produced in the circuit of the line relay 300 which retracts its armature a plurality of times in response thereto. At each retraction of its armature 315, an impulse of current is sent to the rotary magnet 312 in multiple with the slow acting relay 307. The rotary magnet 312 operates to rotate the switch wipers into engagement with the contact set associated with the night service number which, we will assume, are the bank contacts 379-381, inclusive. The springs 338 are forced into engagement by the rotary cam on the switch shaft when the switch-wipers are rotated into engagement with the night service number. A circuit is thereby completed for relays 304 and 305 both of which operate to prepare points in the repeating circuit. The slow acting relay 307 which is energized in multiple with the rotary magnet operates to connect the test wiper 361 to the test relay 306. If the night service number is busy, there will be a ground potential present on back contact 380 engaged by the test wiper 361 and a circuit will be completed for the test relay 306. This relay, upon energizing, establishes a locking circuit for itself and places a busy tone on the calling subscriber's line. Upon hearing this tone, the night watchman at substation A will replace his receiver upon the switchhook thereby replacing the connector H' and the line switch C in the usual manner.

However, it will be assumed in the present case that the night service number was idle when connection therewith was attempted by the connector H'. Under these circumstances, there will be no ground present on the test contact 380 engaged by the test wiper 361 and no circuit will be completed for the test relay 306. Then, following the deenergization of the slow acting relay 307, a circuit is completed for the switching relay 308 extending from ground on release trunk conductor 320 by way of armature 340 and its back contact, lower winding of the switching relay 308, back contact and armature 346, normally closed springs controlled by armature 350, conductor 129, and thence through the winding of the relay 91 to battery. Re-

lays 91 and 308 energize over this circuit, relay 91 operating to remove the bells 98, 99 and 100 from the bridge of the trunk conductors at armature 92 and at armature 93 completing a circuit for busy visual 29 and the cut off relay 26. A branch of this circuit also extends by way of the release trunk conductor 136 to multiply connected test contacts in the banks of the local connector selector repeaters whereby the trunk line is protected from intrusion in the usual manner. Relay 308 upon energizing, establishes a locking circuit for itself at armature 349 and at armatures 348 and 352 completes the operating circuit of the outgoing line switch C³ over the following path: ground by way of armature 625 and its back contact, trunk conductor 429, ring of jack J', ring of plug P², ring of plug P³, ring of jack J⁴, conductor 130, bank contact 381, wiper 362, front contact and armature 352, armature 337, and its front contact, front contact and armature 316, lower winding of the impedance coil 303, armature 335 and its front contact, front contact and armature 334, upper winding of the impedance coil 303, back contact and armature 345, front contact and armature 335', armature 348 and its front contact, wiper 360, bank contact 379, conductor 128, tip of jack J⁴, tip of plug P³, tip of plug P², tip of jack J', trunk conductor 428, armature 626 and its back contact, and thence through the winding of the line relay 602 of the line switch C³ to battery. The line relay 602 is energized over this circuit and the line switch C³ operates in the usual manner to select an idle trunk line extending to a main exchange first selector.

When the calling device at substation A is operated for the remaining digits of the main exchange subscriber's number a series of interruptions is produced in the circuit of the line relay 300 of the selector connector repeater H'. At each retraction of its armature 316 these impulses are repeated to the line relay of the first selector and the succeeding connector. The connection is thus completed to a main exchange subscriber in the well known automatic manner. When the conversation is terminated the operated switches will be released, upon the calling and called subscribers replacing their receivers upon the switchhook, in the usual manner.

Having fully described and ascertained the features of the invention, what is considered to be new and desired to have protected by Letters Patent will be pointed out in the appended claims.

What I claim as my invention is:

1. In a telephone system, a trunk line extending to an operator's position and provided with two branches, one of said branches normally disconnected, a visual signal for one branch and an audible signal

for the other branch, means for seizing said trunk line and for operating said visual signal, and operator controlled means for connecting said other branch, said last means 5 also effective to permit the next call over said trunk line to operate said audible signal without operating said visual signal.

2. In a telephone system, a trunk line, means for seizing said trunk line at one end 10 and for extending connections thereover, a pair of branches for the other end of said trunk terminating in jacks before an operator, a signal for one of said branches normally operative in response to calls there- 15 over, a signal for the other branch normally inoperative, and operator controlled means for rendering said normally operative signal inoperative and for rendering said normally inoperative signal operative.

20 3. In a telephone system, a plurality of subscribers, an operator's position, a trunk line having two branches extending to said operator's position, a signal common to all said plurality of subscribers, means for seizing said trunk lines and for signalling the operator at the said position over one branch in response to a call over said trunk line, operator controlled means for routing the next call over the other branch to operate 25 said common signal, and means under the control of any one of said plurality of subscribers for connecting with said trunk and stopping the operation of said common signal.

35 4. In a telephone system, a trunk line extending to a private exchange, subscribers' stations in said exchange, automatic switches in said exchange for completing local connections between said stations, a signal common to all of said subscribers' stations operable when calls are received over said trunk line, and means under the control of one of said subscribers for answering any call over said trunk line by operating one of said 40 switches to connect with said trunk in response to the operation of said signal.

5. In a telephone system, a trunk line, means for seizing said trunk line and extending connections thereover, a pair of 50 branches for one end of said trunk terminating in jacks before an operator, a signal for one of said branches normally operative in response to calls thereover, a signal for the other branch normally inoperative, means 55 controlled by the operator for rendering said last signal operative for all incoming calls, a plurality of subscribers having access to said trunk line, and means controlled by any of said subscribers for seizing said last 60 branch in response to the operation of the said last signal.

6. In a telephone system, a manual exchange, and an automatic exchange, automatic switches in the automatic exchange 65 for completing connections to subscribers'

lines, a trunk line connecting said exchanges and accessible to said automatic switches, means for calling the automatic exchange over said trunk line from the manual exchange including means for operating a signal associated with the said trunk without making the trunk line busy to said switches, and means for answering the call by operating one of said switches to connect with said trunk line.

7. In a telephone system, main and branch exchanges, automatic switches in the branch for completing local connections, a trunk line and operator's equipment for completing main to branch connections, an auxiliary 75 night service jack connected with said trunk lines, a local trunk line terminating in said switches, a night cord for connecting said jack with said local trunk line, and a signal in bridge of said local line to notify parties 80 at the branch when an incoming call is received.

8. In a telephone system, main and branch exchanges, a trunk line and branch operator's equipment for handling main to branch 85 exchange calls, an auxiliary night service jack connected with said trunk line, a local trunk line, a night cord for connecting said jack with said local trunk line, a signal associated with said local trunk to notify a 90 party at the branch that a call has been received, and an automatic switch at the branch operable by said party to connect with said local trunk line to answer the call.

9. In a telephone system, automatic 100 switches, two classes of subscribers' lines having access to said switches, a trunk line accessible to said switches, service restricting means whereby the subscribers on one class of lines are prevented from operating said switches to connect with said trunk line, a normally open branch of said trunk line accessible to said switches independent of service restrictions, and means for closing 105 said branch to render the trunk line accessible to both classes of lines.

10. In a telephone system, automatic switches, two classes of subscribers' lines having access to said switches, a trunk line accessible to said switches, service restricting 110 means whereby the subscribers on one class of lines are prevented from operating said switches to connect with said trunk line, a normally open branch of said trunk line accessible to said switches independent of service restrictions, and manually operated switching means for closing said branch so that the subscribers on both classes of lines 115 can obtain connection with said trunk line.

11. In a telephone system, an automatic 120 switch, a trunk line extending to an automatic exchange accessible thereto, a normally energized relay associated with the said trunk line in said automatic exchange, means for operating said automatic switch to seize 125

said trunk line, means then operative for de-energizing said relay, a test terminal for said trunk line in said automatic exchange, and means controlled by the deenergization 5 of said relay for applying a busy potential to said test terminal.

12. In a telephone system, a two way trunk line connecting two exchanges, a relay in the first exchange normally energized 10 over said trunk line to make said trunk line idle, means for reversing the direction of current flow in said trunk line when the same is taken for use at the other exchange, the said relay being responsive to such current reversal to make said trunk line busy, and means operative when said trunk line is taken for use at the said first exchange for opening the circuit of said relay, the said relay being also responsive to such operation 15 to make said trunk line busy.

13. In a telephone system, a trunk line, means for connecting a calling line with said trunk line, an operator's cord circuit for connecting said trunk line with a called line, a disconnect signal at said cord circuit, circuit connections for reversing the flow of current over said trunk line when the calling line is disconnected therefrom, and a relay in said cord circuit momentarily responsive to the said current reversal to control said signal.

14. In a telephone system, a trunk line, means for connecting a calling line with said trunk line, an operator's cord circuit for connecting said trunk line with a called line, a relay in bridge of said cord circuit operated by current flow over said trunk line, means for reversing the direction of current flow over said trunk line when the calling line is disconnected therefrom, the said relay being momentarily deenergized, a supervisory relay, and a circuit for said last relay closed by the momentary deenergization of said first relay.

15. In a telephone system, a trunk line, means for connecting a calling line with said trunk line, an operator's cord circuit for connecting said trunk line with a called line, a relay in bridge of said cord circuit operated by current flow over said trunk line, means for reversing the direction of current flow over said trunk line when the calling line is disconnected therefrom, the said relay being momentarily deenergized, a supervisory relay, a circuit for said last relay closed by the momentary deenergization of said first relay, and a locking circuit for maintaining said last relay energized after the said first relay has again operated.

16. In a telephone system, means comprising two operator's cord circuits and an intervening trunk line for connecting calling and called subscribers' lines, a battery connected in bridge of the first cord circuit, a relay 65 connected in bridge of the second cord cir-

cuit and energized by current from said battery, a supervisory relay associated with the second cord circuit, and normal connections from said battery to the trunk line such that current is reversed in said first relay when 70 the said first cord circuit is disconnected from the trunk, the said first relay being momentarily deenergized to close a circuit for said supervisory relay.

17. In a telephone system, a trunk line, 75 means including an automatic connector switch whereby a calling subscriber can extend his line to said trunk line, means including an operator's cord circuit for extending the other end of said trunk line to a 80 called subscriber's line, a relay in bridge of said cord circuit operated by current flow over said trunk line, means for momentarily stopping the flow of current over said trunk line to deenergize said relay when the calling subscriber hangs up, a supervisory relay, and a circuit for said supervisory relay closed when said first relay is deenergized.

18. In a telephone system, a trunk line, 90 means including an automatic connector switch whereby a calling subscriber can extend his line to said trunk line, means including an operator's cord circuit for extending the other end of said trunk line to a 95 called subscriber's line, a relay in bridge of said cord circuit operated by current flow over said trunk line, means for momentarily stopping the flow of current over said trunk line to deenergize said relay when the calling subscriber hangs up, a supervisory relay, a 100 circuit for said supervisory relay closed when said first relay is deenergized, and a locking circuit for maintaining said supervisory relay energized after the said first relay has again operated.

19. In a telephone system, a trunk line, means including an automatic connector switch whereby a calling subscriber can extend his line to said trunk line, means including an operator's cord circuit for extending the other end of said trunk line to a called subscriber's line, a back bridge relay in said connector for feeding current over said trunk line toward the called subscriber, a high resistance relay in bridge 115 of said cord circuit operated by current flow over said trunk line, the said back bridge relay being irresponsible thereto, means for momentarily stopping the current flow to deenergize said high resistance relay when the calling man hangs up, a supervisory relay and an initial energizing circuit therefor closed by the deenergization of said high resistance relay, a locking circuit for said supervisory relay, a low resistance bridge completed across said cord circuit by said supervisory relay whereby the said back bridge relay is operated when current flow over said trunk line is resumed, and means for preventing the release of said connector 125 130

while the said back bridge relay is operated.

20. In a telephone system, a trunk line, a ring down relay, a condenser and a winding of said relay in a bridge of said trunk line 5 at one end, means for connecting with said trunk line at the other end and for ringing thereover to operate said relay, contacts on said relay for short circuiting said condenser to permit a flow of direct current 10 over said trunk line, a locking winding for said relay cooperating with the other winding, and means for reversing the direction of current flow over said trunk line when the connection thereto is broken, whereupon 15 the two windings of said relay oppose each other and the relay is deenergized.

21. In a telephone system, a trunk line, a battery normally in bridge of said trunk line at one end, a relay having a winding 20 in series with a condenser in bridge of said trunk line at the other end, a switching mechanism for connecting a calling line with said trunk line, means for disconnecting said battery when the connection is 25 established, means in said mechanism for ringing over the trunk line to operate said relay, contacts on said relay for short circuiting said condenser, means responsive to the short circuiting of said condenser for 30 stopping the ringing operation and for connecting the battery to said trunk line in the reverse direction, and a locking winding cooperating with the other winding of said relay to hold the same energized until 35 the said switching mechanism is disconnected from the trunk line and the battery connection thereto is restored to normal, whereupon the two windings of said relay oppose each other and the relay is deener- 40 gized.

22. In a telephone system, a main exchange and a branch exchange, a jack ending trunk line connecting said exchanges, plug ending cord circuits in both exchanges 45 for completing main to branch exchange connections via said trunk line, means for signalling the branch operator over the trunk line, means for giving the main exchange operator answering supervision 50 when the branch operator responds, means whereby the branch operator after she has completed the connection can leave the trunk line without giving the main exchange operator a disconnect signal, means for giving 55 the branch operator answering supervision upon the response of the called subscriber, and means for giving both operators disconnect supervision when the called subscriber hangs up his receiver.

60. 23. In a telephone system, a main exchange and a branch exchange, a jack ending trunk line connecting said exchanges, plug ending cord circuits in both exchanges for completing main to branch exchange 65 connections via said trunk line, means for

signalling the branch operator over the trunk line, means whereby the branch operator can plug a cord circuit into said trunk without giving answering supervision to the main exchange operator, means 70 responsive to the actuation of the listening key in the cord circuit for giving the main exchange operator answering supervision, means whereby the branch operator can restore the listening key after completing the 75 connection without giving the main exchange operator disconnect supervision, means for giving the branch operator answering supervision upon the response of the called subscriber, and means for giving 80 both operators disconnect supervision when the called subscriber hangs up his receiver.

24. In a telephone system, means for connecting calling and called subscribers' lines comprising a trunk line and an operator's 85 cord circuit, a battery in bridge of said trunk line, high and low resistance relays connected in series across the talking strands of said cord circuit, the low resistance relay being inoperative, means controlled by the listening key for short circuiting said high resistance relay to operate the low resistance relay, means controlled by the low resistance relay when operated for also short circuiting said high resistance relay whereby the 90 low resistance relay can remain operated after the listening key is restored, and a relay operated on the response of the called subscriber for opening the circuit of said low resistance relay to deenergize the same. 100

25. In a telephone system, a connector switch, a telephone line accessible thereto, a relay in said switch, a test contact for said telephone line connected to the winding of said relay, means for operating said switch 105 into engagement with said line, and means then operative for energizing said relay to extend a connection to said telephone line.

26. In a private branch exchange, connector switches, a conference line having 110 multiply connected line terminals in said switches, non-multiplied test contacts for said line in said switches, a switching through relay in each switch controlling the talking conductors, and a connection in each switch from the test contact associated with said line to the switching relay. 115

27. In a telephone system, a trunk line, switching mechanism for connecting a calling line with said trunk line at one end, means including an operator's cord circuit, and an automatic connector switch for extending the other end of said trunk line to a called line, a battery connected in bridge of the talking circuit at said switching mechanism, and direct metallic connections for supplying current from said battery over said trunk line and through the said cord circuit and connector switch to the transmitter at the station on the called line. 120 125 130

28. In a telephone system, a first exchange, a second exchange, a trunk line connecting said exchanges and terminating in a jack at the second exchange, a line relay

- 5 at the second exchange energized over the trunk when the same is taken for use at the first exchange, a call signal operated by said relay, a cut off relay energized over the sleeve of said jack when the call is answered, 70
 10 the said line relay being deenergized to extinguish the signal, and means operative to prevent the reoperation of said signal and to place a busy potential on said jack in case disconnection is effected at the second
 15 exchange while the trunk is still held at the first exchange.

29. In a telephone system, a trunk line provided with two branches, one branch terminating in a jack and the other branch 20 terminating in the bank of an automatic switch, means for seizing said trunk line at the end opposite said branches, and a relay deenergized responsive to such seizure for causing a busy potential to be applied to 25 only one of said branches.

30. In a telephone system, a trunk line provided with two branches, automatic switches for connecting with either branch, means for seizing said trunk line at the un- 30 divided end thereof, means responsive to such seizure for applying a busy potential to one of said branches, and means for causing one of said switches to seize the other branch of said trunk line when said first
 35 branch is busy.

31. In a telephone system, a trunk line provided with two branches, an automatic switch having access to said trunk line, means for causing said automatic switch to 40 seize said trunk line, means responsive to said seizure for applying a busy potential to one of said branches, and another automatic switch having access to and means for signaling called lines then operable for 45 seizing the second branch of said trunk line.

32. In a telephone system, a two-way trunk line extending between two exchanges, a relay in the first exchange normally energized over said trunk line to maintain said 50 trunk line idle, an automatic switch for seizing said trunk at the second exchange, and means responsive to such seizure for deenergizing said relay.

33. In a telephone system, a two-way trunk connecting two exchanges, a relay at the first exchange normally energized in series with said trunk, means for seizing said trunk at the second exchange, said means effective to deenergize said relay to 60 make the trunk line busy at the first exchange, and means responsive when the trunk is seized at the first exchange for opening the circuit of said relay for the purpose specified.

65 34. In a telephone system, a two-way trunk

line, means at one end of said trunk line responsive to normal current flow thereover for maintaining said trunk line in idle condition, an automatic switch for connecting with said trunk line at the other end, and 70 means for reversing the current flow in said trunk line when the same is taken for use at the other end for making the trunk line busy.

35. In a telephone system, a two-way trunk 75 line connecting two exchanges, a polar relay in one exchange normally energized over said trunk line to make said trunk line idle, an automatic switch in the other exchange for connecting with said trunk line, and 80 means for reversing the direction of current flow in said trunk line when the same is taken for use at the other exchange, the said relay being responsive to such current reversal to make the said trunk line busy. 85

36. In a telephone system, a two-way trunk line connecting two exchanges, means in one exchange for maintaining a current flow over said trunk line in one direction when the trunk line is idle and in the opposite 90 direction when the trunk line is in use, said means comprising a line switch for extending calls from said trunk line and a connector switch for extending calls to said trunk line, and a polar relay in the second exchange 95 responsive to current flow over said trunk line for maintaining the same idle or busy under the conditions named, respectively.

37. In combination, a line, a line relay 100 bridged across said line, a signal, a circuit for said signal closed by said line relay, a cut-off relay for disconnecting said line relay to deenergize the same and open said circuit, a slow-acting relay energized by said cut- 105 off relay, and contacts on said slow relay for transferring said circuit from the said signal to the winding of the slow relay, whereby if the cut-off relay is deenergized and the line relay is again energized before the slow 110 relay falls back the signal will be prevented from operating.

38. In a telephone system, a trunk line, a ring down relay, a condenser and a winding of said relay in a bridge of said trunk line 115 at one end, means for ringing over said trunk line to operate said relay, contacts on said relay for short circuiting said condenser to permit a flow of direct current over said trunk line, a locking winding for 120 said relay cooperating with the other winding, and means for reversing the direction of current flow over said trunk line, whereupon the two windings of said relay oppose each other and the relay is deenergized. 125

39. In a telephone system, main and branch exchanges, a trunk line connecting said exchanges, switching mechanism in the main exchange for connecting a calling line with said trunk line at one end, means in- 130

cluding an operator's cord circuit, and an automatic connector switch for extending the other end of said trunk line to a called line in the branch exchange, a battery connected in bridge of the talking circuit at said switching mechanism, and direct metallic connections for supplying current from said battery over said trunk line and through the said cord circuit and connector switch to 10 the transmitter at the station on the called line.

40. In combination, a line, a signal for said line, a relay normally in bridge of said line, a circuit for said signal closed by said 15 relay, means for removing said relay from in bridge of said line, said means also effective to cause the disconnection of said signal, and means effective should the line relay be again connected to and operated over said bridge 20 within a predetermined time for preventing the reoperation of said signal.

41. In combination, a line, a jack, a signal for said line, a line relay bridged across said line and operative to close a circuit for said 25 signal without applying a busy potential to said jack, means for removing said relay from in bridge of said line, said means also effective to cause the disconnection of said signal, and means effective should the line 30 relay be again connected to and operated over said line within a predetermined period for applying a busy potential to said jack and for preventing the reoperation of said signal.

42. In a cord circuit, a bridge across the two talking strands including a relay in series with a resistance, said resistance being sufficiently high to prevent said relay from energizing by current flow over said talking 40 strands and through the bridge, operator controlled means for temporarily short-circuiting said resistance to energize said relay, and contacts on said relay for short-circuiting said resistance.

43. In a cord circuit, a bridge across the two talking strands including a relay in series with a resistance, said resistance being sufficiently high to prevent said relay from energizing by current flow over said talking 45 strands and through the bridge, operator controlled means for temporarily excluding said resistance from the bridge circuit, and means operated by said relay for maintaining said resistance excluded after the said 55 first means is restored.

44. In a cord circuit, a bridge across the two talking strands including a relay in series with a resistance, said resistance being sufficiently high to prevent said relay from 60 energizing by current flow over said talking strands and through the bridge, operator controlled means for temporarily excluding said resistance from the bridge circuit, means operated by said relay for maintaining said resistance excluded after the 65

said first means is restored, and means in said cord circuit for temporarily opening said bridge to deenergize said relay, whereby the bridge is restored to normal condition when said last means is restored. 70

45. In a cord circuit, two condensers included in the two talking strands, respectively, two relays connected in shunt of said two condensers, respectively, and two supervisory devices controlled by said two 75 relays, respectively.

46. In a cord circuit, two condensers included in the two talking strands, respectively, two relays connected in shunt of said two condensers, respectively, a supervisory 80 device controlled by one of said shunt relays, a relay bridged across said talking strands, and a supervisory device controlled jointly by said bridge relay and the other shunt relay. 85

47. In a cord circuit, continuous conductors connecting the tip and ring contacts of the plugs, respectively, to permit a flow of current through said cord circuit, a relay included in series with each conductor, and a bridge across said conductors. 90

48. In a cord circuit, continuous conductors connecting the tip and ring contacts of the plugs, respectively, to permit a flow of current through said cord circuit, a relay included in series with each conductor, and a bridge across said conductors, said bridge being connected to one conductor at a point between the associated relay and answering plug and to the other conductor at a point between the other relay and the calling plug. 95

49. In a cord circuit, continuous conductors connecting the tip and ring contacts of the plugs, respectively, to permit a flow of current through said cord circuit, a relay included in series with each conductor, a bridge across said conductors, said bridge being connected to one conductor at a point between the associated relay and answering plug and to the other conductor at a point between the other relay and the calling plug, a relay in said bridge, and a supervisory relay controlled jointly by said bridge relay and one of said series relays. 100

50. In a telephone system, two exchanges, a trunk line connecting said exchanges, means including said trunk line and a double plug ending cord circuit in each exchange for connecting a calling line in the first exchange with a called line in the second exchange, means for supplying talking current to the called line from the cord circuit in the first exchange through the cord circuit in the second exchange, means for displaying disconnect signals at both cord circuits when the called party hangs up, and means for displaying a second disconnect signal at the cord circuit in the second exchange when the connection is pulled down at the first exchange. 115

51. In a branch exchange, an automatic connector switch, a trunk line extending from said branch exchange to the main exchange, a branch of said trunk line accessible to said switch, a second branch of said trunk line normally inaccessible thereto, and a cord circuit for connecting said second branch to the bank of said switch. 55
52. In a telephone system, a two way trunk line, a polarized relay bridged across said trunk line at one end and held in operated position by current flow thereover, means for reversing the direction of current flow when said trunk line is connected with 10 at the distant end to deactivate said relay, busying means controlled by said relay when deactivated, means for opening the circuit of said relay when the trunk line is connected with at the near end, and means 15 effective in the second case for preventing the deactivation of said relay from operating said busying means. 20
53. In an automatic connector switch, a line relay, an operating magnet, a circuit 25 for said magnet controlled by said relay, a back bridge relay, a ring cut-off relay, and a branch of said circuit extending to said back bridge relay and controlled by said ring cut off relay. 30
54. In a telephone system, means including an automatic connector switch for extending a connection from a calling to a called line, a back bridge relay in said connector, a second relay associated with the 35 called line and maintained energized in series with said back bridge relay by current supplied through the winding thereof, and means in said connector responsive to an act of disconnection by the calling party 40 for closing a shunt path for said current to deenergize said second relay. 55. In a telephone system, a trunk line, a connector switch for extending a calling line to said trunk line, an operator's cord 45 circuit for extending said trunk line to a called line, and circuit arrangements such that the release of said switch is controlled, first, by the operator while extending the connection, second, by automatic means in 50 said cord circuit while awaiting the response of the called party, third, by the called party during conversation, and fourth, by 55
- automatic means in said cord circuit rendered effective by an act of disconnection on the part of the calling party. 60
56. In a telephone system, a trunk line extending to an operator's switchboard, means including an automatic connector switch for extending a calling line to said trunk line and for signalling the operator, 65 a back ridge relay in said connector, means controlled by the response of the operator for energizing said relay, operator controlled means for further extending the connection to a called line, means controlled 70 by the called party for maintaining said relay energized, and means for maintaining said relay energized during the interim in case the operator should leave the connection before the called party responds. 75
57. In a telephone system, a trunk line extending to an operator's switchboard, means including an automatic subscriber controlled switch for extending a calling line to said trunk line and for signalling the operator, means controlled by the response of the operator for setting up a current flow of distinctive character over said trunk line, means controlled by the operator for further extending the connection to a called line, 80 means controlled by the called party for maintaining the distinctive character of said current flow, and means effective during the interim for maintaining the distinctive character of said current flow in case the operator should leave the connection before the called party responds. 85
58. In a telephone system, a trunk line extending to an operator's switchboard, means including an automatic directly controlled switch for extending a calling line to said trunk line and for signalling the operator, means controlled by the response of the operator for preventing the release of 90 said switch, operator controlled means for further extending the connection to a called line, and means controlled by the response of the called party for transferring the control of said release preventing means to the 95 called party. 100

In witness whereof, I hereunto subscribe my name this 28th day of February, A. D., 1921.

CLARENCE E. LOMAX.
